FAULT RECORDER FOR AUTOMATIC TELEPHONE EXCHANGE

Fernand Pierre Gohorel, Antony, France, assignor to International Standard Electric Corporation, New York, N. Y., a corporation of Delaware

Application July 3, 1956, Serial No. 595,766

Claims priority, application France July 5, 1955

8 Claims. (Cl. 179—175.2)

The present invention refers to improvements in automatic telephone systems and more particularly to devices for signaling and recording faults capable of affecting the operation of the various members used for the routing of a call.

In certain automatic telephone systems, the members bringing about and controlling the various selections involved in the routing of a call can be divided into two classes: (1) common members, coming into play during the operations involved in hunting for the calling or for the called line, and (2) individual members, capable of being connected temporarily to said common members in the course of said hunting operations. In some exchanges using crossbar switches, the registers send to the various selection stages the selective combinations required for the routing of the call. In each of them, a marker receives these combinations from the register with which it is temporarily associated and brings about the various operations involved in the selection. In such exchanges, the registers constitute the common members and the markers, the individual members.

The faults likely to affect the common members do not concern all the calls routed through said members, because these faults can result from the temporary association of these common members with certain particular individual members whose identity it is of interest to learn. Thus, in the event of a fault, a common member should not be blocked for longer than necessary to record the condition of the main components of said member, as also the condition relative to individual members likely to be connected to the common member involved at the instant the fault occurs.

The invention proposes to prepare, for each fault, a record containing a certain amount of information on the condition of the members in service at the time a fault occurs, this method making it possible to store said records, to use them subsequently according to operating requirements and to determine accurately the causes of the various troubles. Such records can be obtained by means of perforators, by means of teleprinters or by any other information-recording method.

One of the features of the invention is a device for signaling and recording faults likely to affect the various members bringing about and controlling the various selections involved in the routing of a call, arrangements being provided to connect in succession to an auxiliary memory (1) the seized common member and (2) the various individual members temporarily connected to said common member at the moment the fault occurs, the auxiliary memory thereupon sending to a fault recorder the information received and then releasing.

In the course of the routing of a call, the seized common member brings about and controls in succession a certain number of elementary operations during the hunting for the calling or the called line. It is important to make sure that each elementary operation be performed within a specified period of time.

Another feature of the invention lies in associating

with each common member of the exchange a time device controlling the time taken to perform each elementary operation brought about by said common member, said time device putting in calling position, on the banks of a member finder, the common member with which it is associated whenever said member takes more than its allotted time to perform said elementary operation, said member being thereupon connected to an auxiliary memory through the finder.

10 In order to facilitate the finding of a fault, either in a common or in an individual member, it is important to know the condition in which the various components of said members find themselves at the time of the fault.

Another feature of the invention lies in associating a 15 fault wire with each of the main relays or magnets and in providing arrangements that will allow bringing said wire to a characteristic potential revealing, at the instant a fault occurs, the condition of the relay or magnet with which it is associated, it being possible to connect said fault wires, through the member finder, to an auxiliary memory that will then record their characteristic potentials.

It is important to know at the instant a fault occurs the 20 identity of the calling common member and that of the individual members capable of being temporarily associated with it.

Another feature of the invention lies in using the position taken by the member finder to determine the identity of the calling member, an identity that can thereupon be sent to the auxiliary memory, which will record it temporarily.

If the seized common member is temporarily associated with individual members at the time a fault occurs, it is desirable to connect said individual members to the 25 auxiliary memory in order to allow it to record (1) their respective identities and (2) the condition of their fault wires.

Another feature of the invention lies in that, when the connection between the faulty common member and the auxiliary memory has been made, and once said memory is in a position to record the condition of the fault wires of said common member, arrangements are provided to cause (1) the temporary release of the member finder and (2) the sending of a special signal to the seized common member, this signal being thereupon sent by said common member to the various individual members with which it is temporarily associated at the instant the fault occurs, arrangements being provided for then putting in calling position on the banks of the member finder the first of said individual members and for cancelling the temporary release of the member finder, the self-same cycle then recurring for each individual member temporarily associated with said common member, the auxiliary memory recording in succession the identity and the condition of the fault wires of said individual members.

When the recording of the identity and of the condition of the fault wires of the last individual member associated with the common member has ended, arrangements must be provided to release the member finder and to connect the auxiliary memory to a recording device.

Another feature of the invention lies in that, once the identity and the condition of the fault wires of the last individual member seized by the common member have been recorded by the auxiliary memory, the member finder releases after a predetermined period of time, the auxiliary memory then being connected to a fault recorder, sending it all the information it had recorded and thereupon releasing, it being possible to provide arrangements to send to said recorder full information regarding the instant at which the fault occurred.

Generally there is only one member finder for each exchange. It follows from this that it is important that its holding time be reduced to a minimum for each fault recording. Further, the time required by the fault recorder to record fault information can be considerable if it is an electromechanical device such as a perforator, a teleprinter, etc.

Another feature of the invention is to associate a plurality of auxiliary memories with the member finder, this arrangement allowing said member finder to be associated with a free memory while some other memory sends the information received to the fault recorder.

In an automatic telephone exchange comprising common and individual members it may happen that two individual members of different kinds, or else one common member and one individual member, can never be connected together either while hunting for the calling line or while hunting for the called line.

Another feature of the invention lies in using the same elements of the auxiliary memory for temporarily recording the condition of the fault wires of a plurality of common or individual members when said members cannot be connected simultaneously either while hunting for the calling line or while hunting for the called line, the purpose of this arrangement being to reduce substantially the size of the memories used.

Whenever a common member controls only a small number of elementary operations, it is superfluous to provide for such common member a time device to control the building-up time of each of said operations.

Another feature of the invention lies in associating with a common member controlling only a small number of elementary operations a time device that will control the time taken to perform the whole of said operations, the operation of that device placing said member in calling position on the banks of the member finder in order to connect it finally to the auxiliary memory.

Various other features of the invention will appear from the description that follows, given as a nonlimitative example with reference to the accompanying drawing, in which:

Figs. 1 and 2 are wiring diagrams used to explain the general operation of the system;

Figs. 3 to 8, a schematic of the devices provided for finding and recording faults in the common or individual members of the exchange;

Figs. 9 and 10, summary tables that allow explaining the method of wiring certain members of the above-mentioned device;

Figs. 11 and 12, a simplified diagram of the recording form;

Fig. 13 shows how to associate Figs. 3 to 8;

Fig. 14 shows how to associate Figs. 11 and 12.

The general operation of the system will now be described with reference to Fig. 1.

Throughout what follows, the term "connector" will be used to designate a set of members arranged at the end of a circuit or of a line and intended to connect said circuit or said line to a particular equipment of the exchange.

In the description that follows, we shall first of all recall in summary fashion the arrangement of the members and the methods for routing calls in an automatic telephone exchange using crossbar switches or "multi-selectors." Detailed descriptions of exchanges of this type may further be found in French patent applications 666,786 and 667,417 and in certificate-of-addition application 687,167/1,069,160, filed by applicant on April 7, 1954, April 16, 1954, and March 9, 1955.

The automatic switchboard involved serves a certain number of subscribers divided up into groups. A group-selecting means chooses the group comprising the called subscriber, a line-selecting means choosing the called subscriber from among all the subscribers in the group involved.

When the calling subscriber *Ab1* removes his handset, his line equipment *L1* is connected to common test relays *R, C, T*. The latter determines the split of call finders *CA* comprising free call finders having access to free registers. The common test relays are thereupon connected to a tester *T* charged with hunting for a free call finder having access to a free register in the call-finder split determined as above indicated. The tester is connected to one of the line markers *ML1* controlling the line-selecting means to which the calling subscriber is connected.

Register connector *JE*, associated with the call finder *CA1* chosen, is seized and is connected to a register *E* through a register finder *CE1*.

The marker seized then places the line in calling position on the banks of the final selectors *ST1* serving the calling subscriber. The connector *CST1* serving the final selectors places in calling position on the banks of call finders *CA1* the free final selectors *ST1* capable of routing the call.

The call-finder connector *CCA1* of the chosen call-finder frame hunts for a final selector *ST1* among those in calling position, at the same time that the hunting for the calling subscriber's line is done by the final-selector connector *CST1*.

The marker seized causes the energization of the call-finder's connecting magnet, then that of the final selector's connecting magnet and thereupon that of the calling subscriber's cut-off relay.

The calling subscriber is now connected to a register *E*, while the tester and the marker are released.

The calling subscriber then dials the called number. As soon as register *E* has received the number's portion enabling it to control the group-selecting operations, it is connected to a group-selection receiver *RG* through a receiver connector *CR*. Register *E* then sends in coded form to this receiver the selective combinations required for the control of the group selection. After learning the identity of the group-selecting means *SG* seized by register connector *FE*, receiver *RG* is connected to one of the two markers *MG* (only one of them is shown in Fig. 1) serving said group-selecting means *SG*, over connecting circuit *mcg*.

The marker *MG* seized receives from receiver *RG* the coded information relative to the group selection and controls said selection through first-selector connectors *CSP* and second-selector connectors *CSS*.

Marker *MG* and group receiver *RG* thereupon release.

When the register has received the whole called number, it is connected to a line receiver *R2* through receiver connector *CR* and sends it in coded form the selective combinations required for controlling the line-selection operations. Receiver *R2* is connected to one of the two markers *M2* (only one of them is shown) serving the line-selecting means to which the called subscriber is connected. Marker *M2* chooses a final selector *ST2* capable of routing the call and, after making sure that the line of called subscriber *Ab2* is free, controls the establishment of the connection through fifties selector *SC2* and final selector *ST2*. The called subscriber is rung and the connection is established in accordance with a known method, while marker *M2*, receiver *R2*, register *E* and receiver connector *CR* release.

Let it be explained further that calls coming from circuits are routed either by a group-selecting means and a line-selecting means, in the case of a call over an incoming circuit, or only by a group-selecting means, in the case of a call passing in transit through the exchange involved. Moreover, calls to special services are routed by a line-selecting means (to which the calling subscriber is connected) and a group-selecting means as appears from examination of Fig. 1, where said special services are represented by a line provided with a jack referenced *SCP*.

Let it be recalled that, save in the case of local calls or of incoming calls, register *E* is always associated with

a translator D through a translator connector CD, as moreover explained in detail in the aforementioned patent applications.

As appears from the foregoing description, it will be noted that two consecutive stages can be distinguished in the sequence of operations that develop upon the establishment of a local connection.

The first stage extends from the moment the calling subscriber lifts his handset to the connection of said subscriber to a free register. The second stage involves the dialing proper by the calling subscriber and the hunting for the called subscriber.

In other words, it may be said that the first stage involves the hunting for the calling line, this hunting taking place under the control of two essential members: tester T and line marker ML1. The second stage occurs under the control of the register, associated in succession either with a group receiver and a marker, in the course of the group-selection operations, or with a line receiver and a marker, in the course of the line-selection operations.

In order to ensure proper operation of the various members involved in the establishment of a connection, some of them comprise time devices whose function is to check that each elementary operation controlled thereby is performed in less time than a predetermined limit. The above-mentioned time devices are included in the common members involved in the establishment of a connection. It will be recalled that these common members are essentially the tester and the register.

These members therefore comprise for this purpose a time relay whose operating time is greater than that of the elementary operations that normally must develop without incident. As regards the tester, the number of elementary operations that must develop from the seizure of said tester to the connection of the calling subscriber to a register is relatively small. It follows that for reasons of simplification and of economy the tester or testers are provided with a time relay that is switched in from the seizure of said tester, the return to zero of this relay occurring only once—upon the release of the tester. Stated otherwise, said time relay checks the total holding time of the tester or, what amounts to the same, the sum of the elementary times required for the building up of the elementary operations controlled by said tester.

As regards the register, the number of elementary operations it controls is large and said operations are of a highly different nature. Thus, in the case of a local call the register controls two selection operations, one group-selection operation and one line-selection operation, and said operations can in turn be subdivided into elementary operations. For this purpose, arrangements are provided to return the time device to zero a number of times in succession, the number of returns to zero being equal to the number of elementary-operation cycles controlled by the register.

Therefore, the fact that the time device operates, either in a tester or in a register, shows the existence of one or more faults preventing an elementary operation either from being performed within a predetermined time or from being performed at all, without however affording the possibility of tracing the fault, which latter can occur either in a common member or in an individual member (marker, receiver . . .) temporarily associated with said common member.

It should be pointed out in this connection that a given fault can occur in a common member, in a tester, for example, when the latter is associated with a given marker, although with other markers the selection operations will be performed without incident. This amounts to saying that such faults result from the association of two quite specific members, while each of said members, if separately associated with other members in good condition, will not give rise to any operating trouble.

In order to be able to trace the fault, each member, be it common or individual, has been provided with a

certain number of so-called fault wires, normally isolated but brought successively to fixed potentials and thus characterizing the successive phases of the trouble in a given cycle of elementary operations, the application of voltage to these characteristic wires being effected by the relays whose function it is to control the starting of the various elementary-operation cycles mentioned above.

Whenever a fault occurs in a common or an individual member, the time device comprised in the common member, whether associated or not with an individual member, operates and brings said common member into calling position on the banks of a member finder C (Fig. 2).

To explain, it will be assumed, as an example, that in the course of putting through a local call the time device comprised in the seized register operates at such a moment that said register has just been associated with a line-selection marker (M2 in Fig. 1). This assumes by implication, as follows from the foregoing description, that register E has first been associated with a line receiver (R2 in Fig. 1).

From the operation of the time device, a special potential is applied to wire $a2$ (Fig. 2), this bringing register E into calling position on the banks of member finder C. Member finder C can be associated with two identical memories. As soon as it is seized, it tests both memories simultaneously in order to determine which of them will be used for recording the fault. Once it has chosen one of the two memories (such as M in Fig. 2), the member finder connects the fault wires, such as $d2$, issuing from register E to memory M through a coding device referenced K in Fig. 2. This coding device is used to send to memory M coded information that will allow determining the identity of the calling register E. Once the connection between register E and memory M has been made, member finder C sends a characteristic potential to register E over an identification wire $i2$. The bringing of this characteristic wire to a special potential serves two purposes: (1) to start in member finder C a time device that is to cause the slow release of said member finder C and (2) to cause in succession the bringing into calling position of the individual member or members that may happen to be seized by register E at the instant involved.

The above-mentioned identification wire $i2$ is extended to line receiver R2 (wire i_2^2) and to line marker M2 (wire i_2^3), since at the instant involved a connection is established between register E, line receiver R2 and line marker M2 through a receiver connector not shown in Fig. 2. The bringing of identification wire $i2$ to a characteristic potential causes in each of the two individual members presently seized by the register the operation of calling relays comprised in each of said members.

Line receiver R2 is immediately brought into calling position on the banks of member finder C, while the bringing into calling position of the marker is deferred, arrangements being provided to delay this bringing into calling position until receiver R2 has been connected to coder K and to memory M.

Member finder C then proceeds to hunt for the calling receiver without first having hunted for a memory. This latter hunting is actually useless, because the capacity of the memories used is such that one memory alone is sufficient to record simultaneously the information concerning a common member associated with two individual members (for example, a register associated with a receiver and with a marker). It follows that the memory chosen first, at the time register E was brought into calling position, will also be used for the recording relative to line receiver R2 and, subsequently, to line marker M2.

It was pointed out before that the bringing of identification wire $i2$ to a characteristic potential was intended to start the operation of a time device causing the slow release of member finder C. If an individual member, say line receiver R2, is brought into calling position on

the banks of member finder C, the above-mentioned time device is returned to zero. Owing to this fact, the member finder C seized by the register is not released.

As soon as a connection has been established between line receiver R2 and memory M through coder K, the time device releasing the member finder is brought back into operation.

Line marker M2 is then brought into calling position on the banks of member finder C, while the time device releasing said finder C is returned to zero.

In the same manner as previously described in connection with register E, marker M2 is connected to memory M through coder K, while the time device releasing member finder C is brought back into operation.

At this moment common member E and individual members R2 and M2 have just been connected to memory M through coder K. The hunting by member finder C has at present ended. At the end of a certain period, the above-mentioned time device operates and causes the release of finder C.

The release of member finder C involves the seizure of a perforator P. The information recorded in coded form by memory M is then sent to this perforator through connector CR and across a decoder DE.

No description will be given of perforator P, which is of the classical type providing perforated records identical in every respect with those currently used in mechanical recording.

The fact that coded information is sent to perforator P allows reducing considerably the capacity of connector CP.

When recording a fault, it is important to know the day and the time it occurred. Accordingly, a clock H is provided that gives coded information making it possible to learn with every desirable degree of accuracy the instant at which the fault occurred. This information is sent to the perforator through decoder DE.

As soon as it is seized, the perforator starts recording on a recording form. The information recorded in succession on the form is, for the example chosen:

- (1) Information on the instant the fault occurred, that is, the day, the hour, the minute, etc.
- (2) Identity of the calling register.
- (3) Identity of the receiver R2 associated with register E.
- (4) Identity of the marker M2 connected to receiver R2.
- (5) Identity of the first, second and overflow frames to which the marker M2 is connected.

(6) Position of the components of the common member (register E) and of the individual members (receiver R2, marker M2). As is known, the position of these components is given by analyzing the above-mentioned fault wires.

Once all this information has been recorded on the recording form, the latter is ejected by the perforator, which then returns to normal and is released, its release entailing that of memory M. The fault-recording device is free again.

It has been previously assumed that when register E was brought into calling position, it was connected to a line receiver R2 and to a line marker M2. It may happen, for example, that the connection of receiver R2 to marker M2 has not actually been made when register E is brought into calling position on the banks of member finder C. In that case, all the above-described operations up to the instant receiver R2 is seized developed in identical fashion. It has been pointed out before that from the connection of receiver R2 to memory M, the time device bringing about the slow release of member finder C was brought back into operation. Considering that no marker is seized by the receiver involved, the above time device cannot be returned to zero and it will start operating at the end of a certain period of time, thus causing the release of finder C and the connection of memory M to

perforator P in accordance with a method identical with the one already described.

When the calling common member is a tester, the fault finding and recording operations develop in identical fashion. The essential difference is due to the fact that the tester can be connected only to a line marker.

A detailed description of the operation of the system will now be given with reference to Figs. 3 to 8.

In the descriptions that follow, the relay windings are identified by a letter combination comprising two capital letters followed by one or more small letters. The first capital letter characterizes the equipment in which the relay is used. All relays forming part of one and the same equipment therefore bear a reference beginning with one and the same letter. For equipment and wiring reasons, the relays of each equipment are divided into groups, all the relays in one group being fixed on the same bar. The second reference capital letter of the relays characterizes this bar. All the relays of one and the same bar therefore bear one and the same second capital letter. The small letters following the first two capital letters in the reference of a relay designate the contact assemblies associated with the respective relay. On one and the same bar, the contact assemblies of the various relays are referenced in alphabetical order. Thus, on bar A of equipment C, if the first two relays each have two contact assemblies, and the next two only one each, the references used will be:

30 First relay—CAab
Second relay—CAC
Third relay—CAD
Fourth relay—CAe

35 The relay contacts are referenced as follows: for a given contact assembly associated with a given relay, the contact references are obtained by having the two capital letters comprising the first portion of the relay reference followed by the small letter characterizing the contact assembly involved and by a figure identifying the contact in the assembly in question. Thus, contacts CAa2 and CAB3 are respectively the second contact in assembly a and the third contact in assembly b of relay CAab.

40 In some cases, for the sake of simplification, similar members or circuits performing identical functions are shown as a single member or circuit of each kind.

Only the first and the last member have been referenced in this particular case, the references being separated from each other by a fraction bar. Thus a relay whose winding is referenced CPA/e actually represents five relays referenced CPA, CPB . . . CPe. Likewise, a relay contact referenced CIAj, 2/11 actually represents the second, third . . . eleventh contacts of relays CIA, CIB . . . CIj, or a total of 100 contacts (10 relays, 10 contacts per relay).

55 To make the drawing clearer, certain wires intended to provide electrical connections between distant members have been grouped into cables. These cables are referenced by capital letters. The wires in a cable are referenced by a small letter preceded by the capital letter identifying the cable.

60 The make-up of a memory, among other things, will be described in what follows. In view of the large number of relays making up this memory, the windings of these latter have been referenced MKm1 . . . MKm104. Each of these relays has one front contact. These contacts have been referenced MKm1/1 . . . MKm104/1, which allows simplifying considerably the references used.

65 As will be seen later on, the member finder is equipped with a multiselector frame. Within this frame are a certain number of selecting magnets.

70 These magnets are divided into two groups: a group of "low" magnets and a group of "high" magnets. These magnets are referenced Csb1 . . . Csb14, Csh1 . . . Csh14, the small letters b and h comprised in the references designating the "low" and the "high" magnets, re-

spectively. The front or back contacts associated with these magnets are referenced $Csb1/1$, $Csb1/2$, the second figure designating the serial number of the contact in the assembly with which it is associated.

The battery normally used for the general supply of the system has its negative pole represented by an arrow; its positive pole is connected directly to ground.

It will be assumed as a nonlimitative example that the particular exchange to which the present invention is applied comprises 5,000 subscribers as a maximum. These subscribers are divided into 10 groups of 500 subscribers each, each group being selected by a group-selecting means SG (Fig. 1) of a group-selecting set. In the case of a local call, the called subscriber is then hunted for by a line-selecting means.

As already pointed out before, the members coming into play in the selection chain of the exchange discussed above can be divided into two kinds:

- (1) Common members—testers, registers.
- (2) Individual members—receivers, translators, markers.

These members, which form no part of the present invention, are represented by rectangles referenced by the following letters:

- (1) E, for the registers (Fig. 4).
- (2) T, for the testers (Fig. 7).
- (3) R, for the line or group receivers (Fig. 5).
- (4) M, for the line or group markers (Fig. 6).
- (5) D, for the translators (Fig. 5).

However, within these rectangles are shown the circuit components required for an understanding of the system.

Before discussing in detail the operation of the various circuits forming the object of the present invention, the code will be explained that is used for recording on the recording forms the various pieces of information that the device can record.

For this purpose, Figs. 10 and 11 shown schematically a recording form identical with those currently used in mechanical recording. As is known, these forms are divided up into a certain number of boxes, each intended to record either partial information or complete information. In practice, each form contains 10 horizontal lines and 80 columns, this providing 800 boxes. However, thanks to a trick currently used, the capacity of these forms can be tripled by providing two additional horizontal lines, which, combined with the 80 columns mentioned above, thus give 160 additional boxes. It should further be explained that the above additional lines are used only in certain special cases where it is necessary to record in a given column some particular information that can depend on a number of parameters. Along this order of ideas may be mentioned for example the case of alphabetical tabulating machine.

As is common usage, the lines are numbered from 0 to 9 from top to bottom and the columns from 1 to 80 from left to right. The additional lines are numbered 11 and 12 and are placed above the 10 normal lines previously mentioned.

As indicated above, a punching is provided in each column for the recording of partial or complete information, a punching that can be effected in any of the ten boxes mentioned above, it being further possible to associate this punching with an additional punching in either of the two boxes of additional lines 11 and 12.

In order to make it easier to understand the method of recording information relative to member faults, hatching is used for the boxes intended to receive punching characterizing either numerical values, such as the number of the receivers or the markers, or else the result of an operating test, such as the presence (punching) or the absence (no punching) of a particular potential on a fault wire, as already stated in the general description of the operation of the system.

The above-mentioned boxes are therefore provided to record either information of a purely numerical nature or

information revealing the presence or the absence of a particular potential on a fault wire.

Other boxes contain small letters characterizing punchings relative to information either of a particular character, concerning the nature of a faulty member, for example, or of a complementary character, concerning an additional box such as those mentioned above.

In order to explain, consideration will now be given to the whole information that can be recorded during fault recording operations.

(1) Column 1: This column is provided to characterize the nature of a faulty member. The letter *w* characterizes the recording of a fault.

(2) Columns 2 to 7: These columns are provided to record the instant of a fault. For this purpose, provision is made to record the day of the month (columns 2 and 3 for tens and units), the hour (column 4 for units and tens), the minutes (columns 5 and 6 for tens and units) and, finally, tenths of a minute (column 7). As regards

20 the recording of hours, it will be noticed that a single column is provided, while the figure representing this magnitude may be comprised between 0 and 23. Discrimination of the tens comprising the hour figure is provided for by providing in the corresponding column (4) a punching 25 in one of the two additional boxes of lines 11 and 12. These punchings, referenced *g* and *h*, are made in accordance with the following code:

(a) Tens digit comprised between 00 and 09, no punching in the additional boxes.

(b) Tens digit comprised between 10 and 19, punching in box *g*.

(c) Tens digit comprised between 20 and 23, punching in box *h*.

(3) Columns 8 and 9: these columns are provided to record the tens and units digits making up the numbers of the registers of the exchange. In principle, the identity of a maximum of 100 registers (number comprised between 00 and 99) is recorded. However, this number can be doubled by providing a punching in an additional 40 box (*i* in Fig. 9).

(4) Column 10: this column is provided for two uses:

(a) To record the category of the receiver or of the translator.

(b) To record the 500-subscriber group with which the line marker is engaged.

These various recordings are punched in box *a* or *b* for the 5000-line group with which the line receivers can be associated (first or second 5000-line group in a 10,000-line exchange), *c* or *d* for identifying the group-selection stages (first or second) to which the group receivers are connected, *e* or *f* for identifying the two translators usually comprised in 10,000-line exchanges, and *j* or *k* for identifying within a thousand the 500 lines of the group serving the called subscriber, this referencing thus serving to identify the two line markers associated with said 500-line group.

(5) Column 11: this column is for recording the numbers of the receivers or of the testers. Further, punchings are made in boxes *l* and *m* to show which of the two testers of the line-selecting means is used in the hunting for the calling line.

(6) Column 12: this column is for recording the number of the thousand of which the line markers and the testers can be connected. In addition, punchings are made in boxes *n* and *o* to show which of the two markers of the group-selecting or of the line-selecting means is used.

(7) Columns 13 and 14: these columns are for recording the numbers of the first and second multiselector frames seized. Since these numbers can be comprised between 00 and 19, additional boxes *p* are punched whenever these numbers are comprised between 10 and 19.

(8) Column 15: this column is for recording the numbers of the overflow multiselector frames that may possibly be used for routing a call.

(9) Column 16: this column is for recording the numbers of call finders. Box *q* is punched whenever the number of the call finder is comprised between 10 and 19.

(10) Column ("skip" column) 17: Since this column is not for recording any information, it is "skipped" by the perforator. The method of skipping this column will not be explained subsequently.

(11) Columns 18 to 39: these columns are used for recording the characteristic potential of the aforementioned fault wires. The corresponding recording is done on lines 0, 1, 2, 11 and 12, as examination of Figs. 11 and 12 will show.

(12) Columns 40 to 80: these columns are not used.

The operation of the system will now be described in detail by assuming that, in the course of putting through a call, the time device comprised in the register E seized shows the holding time of line marker M2 to be abnormally long (Fig. 1). This time device, consisting of a relay in whose coil a condenser discharges, is not shown in the rectangle referenced E in Fig. 4. It will be assumed, by way of example, that the number of registers that can be associated with the fault-recording device forming the object of the invention is 52, as a maximum. These registers are numbered from 00 up for the first and from 51 up for the second fifties. It will be assumed by way of example that the register seized in putting through the call here involved bears the number 00. Rectangle E will therefore represent said register in Fig. 4. In this rectangle are shown only the contacts or the windings of the relay whose presence is necessary for an understanding of the present description.

ED_{k1} and ED_{k2} are the front contacts that close whenever the time device, not shown but comprised in the register, operates owing to the abnormal development of the operations involved in the routing of a call.

In the example chosen, these contacts will therefore close whenever the register is engaged with a line marker through a line receiver and a receiver connector.

The effect of the closing of front contact ED_{k1} is to complete the energizing circuit of ringing relays CB_{def} and CB_{ghi} (Fig. 4): battery, relays CB_{def} and CB_{ghi} in series, back contacts CA_{1/1}, CB_{1/1}, wire Ia through cable I, front contact ED_{k1}, ground.

The pulling up of ringing relays CB_{def} and CB_{ghi} tells member finder C, whose circuits are shown in Figs. 3 to 7, that a register has just detected a fault and has accordingly taken the calling position on the banks of said member finder. The two relays CB_{def} and CB_{ghi} are all there are for the 52 registers that can be associated with member finder C, so that wire Ia, issuing from back contact CB_{1/1}, is multiplied to the 52 registers E, whereof only one is shown in Fig. 4.

In order to determine the identity of the calling register, an identification wire, referenced Ib in rectangle E, is associated with each register. There are therefore 52 wires such as Ib, whose relays CB_{def} and CB_{ghi} provide the connection to selecting magnets CS_{b1} . . . CS_{h13} through their 52 front contacts CB_{d1/10}, CB_{e1/10}, CB_{f1/6}, CB_{g1/10}, CB_{h1/10}, CB_{i1/6}, shown in Fig. 4 as two front contacts referenced CB_{d1/f6} and CB_{g1/i6}.

The following table shows, besides, in order to make it easier to understand the description, the relationship between ringing wires Ib of registers 00 . . . 51 and the corresponding contacts of ringing relays CB_{def} and CB_{ghi}.

Number of registers:	Relay contacts
From 00 to 09	CB _{d1} to CB _{d10}
From 10 to 19	CB _{e1} to CB _{e10}
From 20 to 25	CB _{f1} to CB _{f6}
From 26 to 35	CB _{g1} to CB _{g10}
From 36 to 45	CB _{h1} to CB _{h10}
From 46 to 51	CB _{i1} to CB _{i6}

The energization of ringing relay CB_{def} further causes, through the closing of its front contact CB_{f7}, the en-

ergization of general holding relay DA_{ab}, which pulls up (Fig. 3): battery, resistance CR54, relay CA_{ab}, front contact CB_{f7}, ground.

Before proceeding with this description it is well to explain that the finder used for hunting for faulty common or individual members is of the crossbar type, sometimes called a multiselector.

It will be recalled in this connection that a multiselector frame consists essentially of a certain number of individual selectors each provided with a so-called connecting magnet. With the set of individual selectors are associated so-called selecting bars, each controlled by 2 selecting magnets. The number of selecting magnets is moreover, in accordance with a known method, equal to the number of movable-contact assemblies making up each individual selector.

The contact assemblies are usually identified by assigning them a serial number characterizing their respective azimuths. The fixed-contact assemblies, equal in number to the movable-contact assemblies, are multiplied to one another vertically. It will be recalled that in order to prepare the connection of a movable-contact assembly of a selector to the corresponding fixed-contact assembly, the selecting bar associated with said contact assemblies is operated by energizing the selecting magnet whose azimuth is the same as that of those contact assemblies whose connection it is desired to cause subsequently.

In accordance with a known method, the operation of the selecting bar entails the placing in operating position of all the clutches associated therewith, the number of these clutches being of course equal to the number of individual selectors making up the multiselector frame. Upon energizing thereupon, following the suitable positioning of the selecting bar, the connecting magnet of the previously-designated selector then makes effective the connection of the corresponding movable- and fixed-contact assemblies. It is then possible to release the selecting bar that has just been used, the clutch that served to control the connection remaining in operating position thanks to a well-known mechanical device.

The multiselector frames are so mounted on bays that the selecting bars will be horizontal. In accordance with a known method, a selecting bar can take three positions: a normal position, a first operating position, with the clutch in high position, and a second operating position, with the clutch in low position. Two selecting magnets are associated with each selecting bar. It is well to point out that by design the clutches associated with the selecting bars move in vertical planes and that the two selecting magnets controlling them must be so energized that it will be necessary to energize the lower magnet in order to move the clutch upward and conversely.

Throughout what follows, the selecting magnets controlling the downward and upward movement of the clutches associated with the corresponding selecting bar will be called the "low" and the "high" magnets.

It is known that usually it is the practice to multiply to one another movable-contact assemblies having one and the same azimuth, so as to allow a given azimuth to be served by a plurality of individual selectors. However, for certain special uses, and particularly for the one forming the object of the invention, such multiplying is not done.

It will be assumed in what follows that the multiselector frame used for the embodiment of member finder C consists of 11 individual selectors, each consisting of 28 fixed- and movable-contact assemblies, each assembly comprising 8 contacts. From what has been said before, it follows that there are 28 selecting magnets and 14 selecting bars.

As has been stated in the aforementioned addition applications, the number of fault wires provided in the registers is 21. These wires are referenced Da . . . Du in rectangle E of Fig. 4. The method of connecting these wires is as follows: the 52 registers that can be asso-

ciated with member finder C are divided up into two groups of 26 each. With each register in a group is associated one azimuth, namely, to explain, azimuth 1 with register 00 . . . azimuth 26 with register 25. An identical distribution is provided for the 26 registers of the second group, namely: azimuth 1 for register 26 . . . azimuth 26 for register 51. Stated otherwise, each azimuth is served by two registers, one from the first group of 26 and the other from the second group of 26.

It should further be pointed out that throughout what follows the azimuths in a multiselector frame will be counted vertically from top to bottom. Stated otherwise, the first contact assembly of each selector located at the top of the frame corresponds to azimuth 1, the second to azimuth 2, and so forth.

Moreover, since one azimuth is provided per register in a group of 26 registers, it follows that the registers having an even azimuth (that is to say, the registers bearing the numbers of 01, 03 . . . 25) will be connected by energizing the "low" selecting magnets, because the first azimuth is reached by energizing a "high" selecting magnet. The reverse result is arrived at for the registers having an odd azimuth.

Considering that in each selector the contact assemblies used each comprise 8 contacts, it is necessary to provide 3 individual selectors for each register, this requiring a total of $2 \times 3 = 6$ individual selectors to connect the 52 registers that can be associated with the member finder. Since 8 contacts per assembly are available in each individual selector, it follows that the simultaneous operation of 3 individual selectors will cause the closing of $3 \times 8 = 24$ contacts. Since 21 fault wires must be connected whenever a register is faulty, there are therefore available $24 - 21 = 3$ additional contacts per azimuth and per 3-selector group. As will subsequently be indicated, these contacts are used (1) to send the identity of the calling register and (2) to cause the possible connection of such individual members as may happen to be engaged with the calling register at the instant under consideration.

The 52 identification wires *Ib* previously mentioned are divided up into four 13-wire groups. With each 13-wire group is associated a pilot ringing relay that through its pulling up (1) characterizes the 26-register group comprising the calling register and (2) makes the even-azimuth discrimination. To make matters clear, the table below gives the designation of these relays.

Pilot Relays	Number of Registers	Azimuth
CAs	00, 02 . . . 24	1, 3 . . . 25
CA _T	01, 03 . . . 25	2, 4 . . . 26
CA _u	26, 28 . . . 50	1, 3 . . . 25
CA _v	27, 29 . . . 51	2, 4 . . . 26

It was assumed earlier that the register bearing the identification number 00 had taken the calling position. As has been indicated, this register is associated with an odd azimuth, azimuth 1. From this it follows that pilot ringing relay CAs pulls up (Figs. 3 and 4) following the closing of the 52 front contacts CBd1/10, CBe1/10, CBf1/6, CBg1/10, CBh1/10, and CBi1/6 of ringing relays CBdef and CBghi; battery, relay CAs, resistance CR00, wire Ib relative to register 00, cable I, front contact CBd1, cable I up to register E, wire Ib, front contact ED/2, ground.

It is recalled in this connection that it is possible, as reference to a previously-mentioned table will show, to check that front contact CBd1 is properly used in the case of register No. 00.

The pulling up of pilot ringing relay CAs tells the member finder that the calling register is comprised in the first 26-register group (number comprised between

00 and 25) and that that register is associated with an odd azimuth.

The pulling up of relay CAs completes, through the closing of its front contact CAs1, the energizing circuit of relay CAij, which pulls up (Fig. 3): battery, chain of back contacts Csb1/1, Csh1/1 . . . Csh13/1, Csb14/1, Csh14/1, back contacts Cad2, CAk9, relay CAij, back contact CAR9, front contact CAs1, ground.

The closing of front contact CAs2 completes the energizing circuit of relay CAMno, which pulls up: battery, relay CAMno, back contact CAR8, front contact CAs2, ground.

It has previously been pointed out that the pulling up of ringing relay CBdef had entailed the pulling up of general holding relay CAab through the closing of front contact CBf7.

Through the placing in operating position of its front-back contact CAB1, relay CAab (1) removes the short-circuit from condenser CC1 and (2) completes the energizing circuit of relay CAg8: battery, resistance CR52, relay CAg8, front contact CAB1, ground.

The pulling up of relay CAg8 is slowed owing to the presence of condenser CC1 between the terminals of its energizing winding.

A ground is applied to general holding wire tg by the closing of front contact CAB2.

A holding circuit is completed for relay CAab by the closing of its front contact CAB3; battery, resistance CR54, relay CAab, front contact CAB3, ground.

Before proceeding with this description, a few explanations will be given regarding the selecting magnets. It will be recalled that any selecting bar is common to all the individual selectors forming part of the multiselector frame. There is one selecting magnet for each azimuth, so that, for the 26 azimuths provided for the connection of the registers, there is a total of 26 selecting magnets, comprising 13 "high" and 13 "low" magnets. These 26 magnets, referenced Csb1, Csh1 . . . Csh13, are not all shown in Fig. 3 but they form a chain whose operating principle is well known. It has been pointed out before that the individual selectors each have 28 fixed- and movable-contact assemblies corresponding to 28 azimuths, 26 of which are used for the registers. The two additional azimuths are reserved, as will be seen later on, for the two memories associated with the member finder. There are two selecting magnets, referenced Csb14 and Csh14 in Fig. 3, for these two additional azimuths.

The energization of relay CAMno characterizes the group comprising the calling register (here the first 26-register group) and through the closing of its 26 front contacts CAM1/10, CAN1/10, CAo1/6 prepares the energizing circuits of the 26 selecting magnets Csb1, Csh1 . . . Csb13, Csh13. Fig. 3 shows only the first and the last of these magnets, that is, magnets Csb1 and Csh13.

The closing of front contact CAo7 prepares the energizing circuit of connecting magnet CVa (Fig. 4).

The opening of back contact CAo8 locks in normal position relay CApqr, associated with the second 26-register group.

The pulling up of relay CAij will cause the operation of the selecting magnet corresponding to the faulty register.

The opening of back contact CAi1 prevents the energization of connecting magnet CVa.

The 13 front contacts CAi2, CAi3 . . . CAi8, CAj1 . . . CAj6 are associated with the 13 energizing circuits of "high" selecting magnets Csh1 . . . Csh13. Fig. 3 shows only contact CAj6, associated with selecting magnet Csh13. The effect of the closing of these front contacts is to apply battery potential to all the upper ends of the energizing windings of selecting magnets Csh1 . . . Csh13, so as to allow the energization of the selecting magnet associated with the faulty register.

It is recalled that that register, bearing the number 00, is associated with azimuth 1, to which belongs selecting magnet Csh1.

Magnet $Csh1$ therefore pulls up, its energizing circuit being completed as follows: battery, back $Csb1/1$, front $CAi2$, magnet $Csh1$, front $CAm2$, identification wire Ib previously mentioned, cable I, front $EDk2$, ground.

The opening of back $CAi9$ locks relay $CAk1$ in normal position.

Relay $CAij$ completes a holding circuit for itself through the closing of its front $CAj8$: ground, front $CAi1$, back $CAr9$, relay $CAij$, back $CAk9$, $CAd2$, front $CAj8$, battery.

The closing of front contacts $CAj7$ and $CAj9$ completes the energizing circuit of selecting magnets $Csh14$ and $Csb14$. It will be recalled that these selecting magnets are associated with the two memories that can be connected to member finder C. It will be assumed in what follows that both of these memories are free. In order to prevent a double test upon the seizure of one of these memories, priority has been provided for in the order of their seizure.

An availability relay has in effect been associated with each memory. The contacts of these relays are referenced $MKe1$ and $MKe'1$ in Fig. 8. It will be noticed that the two selecting magnets $Csb14$ and $Csh14$ pull up simultaneously (Fig. 3) owing to the closing of the above-mentioned contacts:

(1) Battery, front $CAj8$, $CAj7$, selecting magnet $Csh14$, back $CDa1$, $CAc1$, wire Aa through cable A, front $MKe1$, ground.

(2) Battery, front $CAj8$, back $Csh14/1$, front $CAj9$, selecting magnet $Csh14$, back $CCa1$, $Cac4$, wire Ab through cable A, back $MKe'1$, ground.

Through the closing of its front $Csh14/1$, magnet $Csh14$ completes a holding circuit for itself and opens the energizing circuit of selecting magnet $Csb14$: battery, front $CAj8$, $Csh14/1$, selecting magnet $Csh14$, ground over a circuit already described.

Selecting magnet $Csh14$ having its energizing circuit broken, it cannot hold and releases, thereby giving priority to selecting magnet $Csh14$, which holds.

Before proceeding with this description, it is desirable to point out that priority has been provided in the case where registers belonging to two different 26-register groups call the member finder at the same time. It is known that relays $CAmno$ and $CApqr$ are actually associated respectively with the first and the second 26-register groups. These relays have their energizing circuits mutually locked through the action of contacts $CAr8$ and $CAo8$ and consequently cannot hold simultaneously, this ensuring the connection of one or the other of two registers that may have taken the calling position simultaneously.

Likewise, two registers of one and the same 26-register group may take the calling position simultaneously. In this case, either one or the other of relays $CAmno$ and $CApqr$ pull up (depending upon the calling 26-register group). Priority is provided by the method of wiring the selecting magnets. In fact, as already pointed out, the latter are so arranged as to form a chain in which only one particular relay can hold even if two registers belonging to one and the same 26-register group should call simultaneously. Examination of Fig. 3 will show for example that, in the event of simultaneous energization of selecting magnets $Csb1$ and $Csh13$, with which are associated the registers bearing the numbers 01 and 24 in the first 26-register group, only magnet $Csb1$ will be able to hold, in view of the fact that, through the closing of its front-back contact $Csb1/1$, it breaks the energizing circuit of all the other selecting magnets ($Csh1 \dots Csh13$).

The selecting magnet $Csh1$ associated with the register bearing the number 00 completes a holding circuit for itself through the closing of its contact $Csh1/1$, not shown in Fig. 3. Further, this contact $Csh1/1$ plays a role identical with that of contact $Csb1/1$, belonging to selecting magnet $Csb1$ (shown in Fig. 3).

Through the closing of their front contacts $Csh1/2$

and $Csh14/2$, selecting magnets $Csh1$ and $Csh14$ complete the energizing circuit of relay CAd , which pulls up (Fig. 3): battery, front $Csh1/2$, $Csh14/2$, relay CAd , ground on general holding wire tg .

It will be noticed that the energization of relay CAd is subject to the pulling up of the selecting magnet associated with the calling register and to the pulling up of the selecting magnet associated with the memory enjoying priority, if both memories are free, or with the only memory free, if one of them is already busy.

The energization of selecting magnet $Csh1$ therefore causes the positioning of the clutch associated with the corresponding selecting bar. It will be recalled in this connection that said positioning corresponds to said memory's rotating upward, since the calling register is, as already pointed out, associated with azimuth 1.

The energization of relay CAd will now cause the starting of the operations involved in connecting the faulty register to the free memory through member finder C.

Through the closing of its front contact $CAd1$, relay CAd prepares the energizing circuit of connecting magnet CVa . Through the closing of its front-back contact $CAd2$, relay CAd completes a holding circuit for selecting magnet $Csh14$ and opens the energizing circuit of relay $CAij$, which releases: battery, front $CAd2$, $Csh14/1$, selecting magnet $Csh14$, ground over a circuit already described.

Before proceeding with this description, the method will be explained of connecting the fault wires of the registers to the banks of the selectors of member finder C. As already pointed out, each register has 21 fault wires, referenced $Da \dots Du$ in rectangle E. Each selector consists of fixed- and movable-contact assemblies each comprising 8 individual contacts, this requiring the use of 3 selectors for the purpose of connecting the 21 fault wires. These selectors are shown in simplified form in Fig. 4. The fixed and movable contact springs forming part of one and the same nest bear the same characteristic figure serving to reference them. Thus the first contact assembly of the first individual selector contains the fixed and movable contacts referenced $Ca0$, $Cb0 \dots Ch0$. These contacts are referenced $Ca1$, $Cb1 \dots Ch1$, while the contact assembly to which they belong forms part of the second selector, etc. For each individual selector it is shown that the movable contacts belong to the first azimuth. The fixed contacts of each selector, which are multiplied to the whole 28 contact assemblies making up the selector, are shown in the form of a vertical bar.

For a predetermined azimuth, the above-mentioned 21 fault wires are wired from left to right so that the first wire will be associated with the fourth contact of the assembly belonging to the first selector and the 21st to the eighth contact of the assembly belonging to the third selector. To make these explanations clear, the method will be explained of connecting the fault wires of the register bearing the number 00, which, as stated, has just taken the calling position on the banks of member finder C. The first wire (Da) is connected to fixed contact $Cd0$, the second, that is, wire Db (not shown), to fixed contact $Ce0$, and the last, that is, wire Du , to fixed contact $Ch2$, belonging to the third selector. Identical wiring is provided for connecting the fault wires of the other registers, associated with azimuths 2, 3, ..., 26. Of course, the above explanations hold as well for the 26 registers of the second group.

The connecting magnets of the individual registers are referenced CVa , $CVb \dots CVf$. The energization of any of these magnets causes, as is known, after the suitable positioning of the clutch, the connection of the 8 movable contacts of the contact assembly designated by the position of the clutch. Connecting magnets $CVa \dots CVf$ are associated with the fixed and movable contacts of the selectors as follows: magnet CVa controls movable contacts $Ca0 \dots Ch0$, magnet CVb

controls movable contacts C_{a1} . . . C_{h1} , and so forth.

The first three selectors, that is, those controlled by connecting magnets CV_a , CV_b and CV_c , are designed to connect the 26 registers of the first group. Likewise, connecting magnets CV_d , CV_e and CV_f , associated with the next three selectors, are designed to connect the 26 registers of the second group.

It has been pointed out before that azimuths 27 and 28 of each selector are associated with the two memories that can be connected to member finder C and that priority exists in the order in which said memories can be connected to said finder. Throughout what follows, the expression "first memory" will be used to designate the memory whose seizure is given priority if both memories are free at the same time when the member finder must connect itself to one of them. One azimuth being reserved for each of the two memories, it will be assumed that azimuth 27 is reserved for the first memory. In other words, this amounts to saying that selecting magnets C_{sh14} and C_{sb14} are associated with the memories bearing the numbers 1 and 2.

According to the foregoing, the fault wires associated with a register can therefore be directed to one or the other of the two memories that can be connected to member finder C. For the purpose of directing them, provision is made to use the 27th and 28th contact assemblies associated with each individual selector. In order to make it easier to understand Fig. 4, such directing has been characterized by adding at the foot of each vertical a directing contact capable of being connected, depending upon which of the selecting magnets associated with azimuths 28 and 27 is energized, either to the control wires of the first memory, grouped in cable Y, or to the control wires of the second memory, grouped in cable Z.

It was assumed before that both memories were free at the instant the faulty register took the calling position. Owing to the priority provided for in the seizure of these memories, it was stated that selecting magnet C_{sh14} had energized and had thereby entailed, as will be seen in what follows, the seizure of the first memory.

It has been pointed out before that the energization of relay CA_{d1} causes the starting of the operations involved in connecting the fault wires of the calling register to one of the two memories capable of being connected to member finder C. The pulling up of relay CA_{d1} causes, as has been stated, the release of relay CA_{i1} . Owing to the closing of back contact CA_{i1} , the energizing circuit of connecting magnet CV_a is completed: battery, right-hand winding of magnet CV_a , back CV_{a2} , front CA_{o7} , CB_{f8} , CA_{d1} , back CA_{i1} , CA_{k1} , ground.

The opening of front contact CA_{i2} . . . CA_{i6} has no effect, because selecting magnet C_{sh1} holds through the closing of its previously-mentioned self-holding contact. The opening of front contacts CA_{j7} and CA_{j9} likewise has no effect at the instant under consideration, selecting magnet C_{sh14} continuing to hold thanks to its front contact $C_{sh14/1}$.

A double operation is performed due to the closing of connecting magnet CV_a . It has been pointed out before that selecting magnets C_{sh1} and C_{sh14} were energized before the instant connecting magnet CV_a energized. It follows from this that fault wires Da . . . De of register E are connected to control wires Ya . . . Ye of the first memory. Connecting magnet CV_a completes a holding circuit for itself through the closing of its front contact CV_{a1} : battery, right-hand winding of magnet CV_a , left-hand winding of magnet CV_a , front CV_{a1} , ground on general holding wire tg .

The opening of back contact CV_{a2} obviously has no effect, owing to the closing of holding contact CV_{a1} . The energizing circuit of connecting magnet CV_b is completed through the closing of front contact CV_{a3} : battery, right-hand winding of magnet CV_b , back CV_{b2} , front CV_{a3} , ground on general holding wire tg .

Likewise, the closing of front contact CV_{a4} completes the energizing circuit of connecting magnet CV_c : battery, right-hand winding of magnet CV_c , back CV_{c2} , front CV_{a4} , ground on general holding wire tg .

The closing of front contact CV_{a5} prepares the grounding of wire c , intended to cause the bringing into calling position of the receiver and the marker that are associated with the register under consideration at the instant of the fault.

Connecting magnets CV_b and CV_c cause, the same way as connecting magnet CV_a , the connecting of the fault wires of the register associated with them (that is, wires $Yf0$ . . . $Ym0$, associated with the individual selector that is controlled by connecting magnet CV_b , and wires $Yn0$ . . . $Yu0$, associated with the individual selector that is controlled by connecting magnet CV_c).

Connecting magnets CV_b and CV_c complete the following holding circuits for themselves through the closing of their front contacts CV_{b1} and CV_{c1} :

(1) Battery, right-hand and left-hand windings of magnet CV_b , front CV_{b1} , ground on general holding wire tg .

(2) Battery, right-hand and left-hand windings of magnet CV_c , front CV_{c1} , ground on general holding wire tg .

The opening of back contacts CV_{b2} and CV_{c2} has no effect, since connecting magnets CV_b and CV_c have each just completed their own holding circuit.

The closing of front contacts CV_{b3} and CV_{c3} completes the grounding circuit for the previously-mentioned wire c : ground, front CV_{a5} , CV_{b3} , CV_{c3} , wire c .

Wire c is connected through the closing of contact CC_0 , associated with the first selector, to ringing cut-off wire b .

The role of this wire will be explained before proceeding with this description. Each register is provided with a relay ED_j , whose energization tells the corresponding register that its fault wires have just been connected to the corresponding control wires of one of the two memories capable of being connected to member finder C. This relay may be regarded to a certain extent as playing a role similar to that of the ringing cut-off relays usually arranged in subscriber-line connectors. The energization of relay ED_j causes by any suitable means the cutting off of relay ED_k , whereof only contacts ED_{k1} and ED_{k2} are shown in Fig. 4.

It is known that in the course of the group- or line-selecting operations the register can be connected to a translator, to a group receiver and marker or even to a line receiver and marker. The connection of said register to the above individual members is effected through connecting members called "connectors." It follows therefore that each register must be wired to the inlets of one or more connectors designed to connect it either to the translators or to the receivers. In Fig. 4 these connectors are represented by dotted-line rectangles, referenced CT for the translator connectors and CR for the receiver connectors.

As can be seen in Fig. 4, the aforementioned ringing cut-off wire b is wired to the inlets of connectors CT and CR.

To wire b therefore correspond, in the translators and the line or group receivers, the wires referenced d and e , capable of being connected to said wire b through connectors CT and CR.

It was previously assumed that at the instant the fault occurred register E was connected to a line receiver R and a line marker M. From this it follows that the receiver connector CR shown in Fig. 4 is in closed position and in particular that the wire b in the register is metallically connected to the wire e in receiver R. The ground applied to wire b through selector CC_0 is therefore extended to wire e and accordingly causes the pulling up of relay RH_m in line receiver R. Each receiver is equipped with a relay RH_m , the pulling up of this relay telling the corresponding receiver that the register with

70

75

which it is temporarily connected has taken the calling position on the banks of a member finder and that the fault wires of said register have just been connected to the corresponding control wires of one of the two memories.

As pointed out before, it is desirable to record on the recording form the identity of a register that has just taken the calling position. The two bank contacts Ca_0 and Cb_0 of the first selector are reserved for this identification.

The two bank contacts Ca_0 and Cb_0 of the first two selectors of each 26-register group are designed to provide the discrimination of the tens and units digits of the number of a faulty register. First of all will be described the method of wiring the wipers providing the discrimination of the units digit in the number of the various registers of a group. It will be recalled that these numbers comprised between 00 and 25 are associated with the azimuths comprised between 1 and 26, inclusive, for the 26 registers of the first group. Likewise, the numbers of the 26 registers of the second group are comprised between 26 and 51 and are associated with the azimuths comprised between 1 and 26, inclusive. The 26 wipers, whereof only one, Cb_0 , is shown in Fig. 4, are connected to 10 units wires such as $Ua1/0$, grouped in cable U. The wiper associated with register 00, corresponding to azimuth 1, is connected to units wire Ua_0 ; likewise, the wiper associated with register 01, corresponding to azimuth 2, is connected to units wire Ua_1 , and so forth. A similar method is used for discriminating the tens unit. To explain, the wipers associated with the registers bearing the numbers 00 . . . 09 are all connected to one and the same tens wire (Da_0); likewise, the wipers associated with the registers bearing the numbers 10 . . . 19 are all connected to the tens wire Da_1 , and so forth. Of course, the wiring of the tens and units wipers belonging to the 26 registers of the second group is done in similar fashion. Two identification-wire groups are thus obtained, one comprising 6 wires, providing for the discrimination of the tens, and the other one 10 wires, providing for the discrimination of the units.

With each identification-wire group is associated a group of coding relays that allows sending the tens and units information in coded form to the memories of the member finder. The code employed is of a well-known type using 5 elements, which are combined 2 by 2 for each piece of information to be sent.

The table that follows will allow determining quickly the relationship between the code elements and the figures to be sent, comprised between 1 and 0.

Code Elements	1	2	3	4	5	6	7	8	9	0
1	X		X		X					X
2		X	X		X	X				X
3			X	X	X	X	X			
4			X			X	X	X	X	X
5	X	X		X			X			

In this table a column is associated with each piece of information to be sent, this making a total of 10 columns, representing the 10 combinations it is possible to make with the above-mentioned code. Likewise, a horizontal line has been associated with each code element, this giving 5 lines, corresponding to the 5 code elements. The result of this is that each column has 5 boxes, whereof only 2 are used for sending the information relative to the particular column involved. The boxes corresponding to the code elements used to send any information are marked with the letter X. Thus, for example, to send the digit 2, an X has been placed in the boxes of lines 2 and 5 of column 2, which means that

the sending of the digit 2 calls for the use of the 2nd and 5th elements of the code involved.

The coding of the information characterizing the units digit of the number of the registers is provided by a group of 8 coding relays referenced $CGa \dots CGh$ in Fig. 4. The coding of the information concerning the tens unit is provided by a group of 5 coding relays referenced $CEa \dots CEe$ in Fig. 4. With each of these relays is associated a front contact: $CGa1 \dots CGh1$, $CEa1 \dots CEe1$. These contacts are so arranged that for each piece of information received they ground two of the five wires $Ca1 \dots Ca5$, $Cb1 \dots Cb5$. The operation of these relays, which form a set well known and currently used in automatic telephony and remote control, will not be described in detail. Coding wires $Ca1 \dots Ca5$ and $Cb1 \dots Cb5$ are grouped into a cable C, terminating at either one or the other of the two memories capable of being connected to member finder C.

It has been pointed out before that the energization of the 3 connecting magnets CVa , CVb and CVc had the effect of grounding wire c. Relay CAf , whose winding is connected between this wire and battery, accordingly pulls up. The pulling up of this relay characterizes in the member finder the fact that the connection between the fault wires of the register and the control wires of the memory has become effective. Through the opening of its back contact $CAf1$, relay CAf breaks the energizing circuit of ringing relays $CBdef$ and $CBghi$. The breaking of the energizing circuit of these relays is actually required in spite of the energization of ringing cut-off relay EDj in register E. In fact, whenever, as is the case in the example chosen, register E is connected to individual members, such as a receiver and a marker, the member finder cannot release and be associated with another register, since the recording of the fault wires located in the receiver and the marker has not as yet been effected. The breaking of the energizing circuit of ringing relays $CBdef$ and $CBghi$ thus prevents any wrong operations of the member finder in case a register had just taken the calling position at the same instant that the recording of the fault wires of the register then engaged with the member finder had just ended. The closing of front contact $CAf2$ makes it possible to render effective the grounding of the wipers Ca_0 and Cb_0 that allows identification of the calling register. General holding relay $CAab$ has its winding short-circuited by the closing of front contact $CAf4$. The other contacts of relay CAf are inoperative at the instant under consideration.

General holding relay $CAab$ having its energizing winding short-circuited, it does not release immediately.

It has been pointed out before that the grounding of wire c had entailed the energization of relay RHm in the line receiver engaged with the register at the instant under consideration (Fig. 5). As is known, the energization of this relay characterizes the fact that the fault wires of register E have been connected to the control wires of the memory associated with member finder C. Relay RHm plays a role identical with that of relay EDk , comprised in register E but not shown, in that it brings receiver R into calling position on the banks of the member finder. Through the closing of its front contact $RHm1$, relay RHm prepares the energizing circuit of common receiver ringing relay CCd .

Before proceeding with the detailed description of the operations involved in hunting for, identifying and connecting the calling receiver R, a description will be given of the make-up and operation of one of the two memories capable of being associated with member finder C. These two memories are further identical, in spite of the fact that priority is given to one of them whenever a common member takes the calling position on the banks of member finder C while both of said memories are free.

The make-up and the operation of the first memory will be discussed throughout what follows. This memory

consists of 104 "memory" relays, shown in Fig. 8 as a single relay referenced **MKm1/104**.

With each memory are associated two seizing relays, referenced **CCabc** and **CChij** for the first memory and **CDabc** and **CDhij** for the second. It will be recalled that at the instant of the suitable positioning of the corresponding selecting magnets, the one at the azimuth of the register chosen and the other at the azimuth of the first memory chosen, relay **CAd** pulls up. Through the closing of front contact **CAd1**, a ground has been applied to wire **mg**, thus causing the energization of connecting magnet **CVa**. Wire **mg** is extended in Fig. 5 to the energizing windings of memory-seizing relays **CCabc** and **CDabc**. It will be recalled that selecting magnet **Csh14** is associated with the first memory and that accordingly front contact **Csh14/3** is closed, with the result that the grounding of wire **mg** entails the energization of the first memory's seizing relay (**CCabc**): battery, front contact **Csh14/3**, winding of relay **CCabc**, wire **mg** across Figs. 5 and 4, front **CAd1**, back **CAi1**, **CAk1**, ground.

Through the opening of its back contact **CCa1** (Fig. 5), relay **CCabc** prevents any untimely energization of selecting magnet **Csb14**. The holding circuit of selecting magnet **Csh14** is completed through the closing of front contact **CCa2**. Relay **CCabc** completes a holding circuit for itself through the closing of its front contact **CCa3**: battery, windings in series of relays **CChij**, **CCabc**, front **CCa3**, ground on general holding wire **tg**.

Relay **CChij**, whose winding is connected in series with that of relay **CCabc**, pulls up.

The general holding relay **MKa** of the first memory has its energizing circuit completed through the closing of front contact **CCa4**. The closing of front contacts **CCa5** . . . **CCa11**, **CCb1** . . . **CCb11**, **CCc1** . . . **CCc11** connects part of the control wires of the memories to the corresponding "memory" relays. These contacts are shown in Fig. 5 as a single contact, associated with cable **C** and referenced **CCa5**.

It has just been pointed out that the closing of front contact **CCa2** completed a holding circuit for selecting magnet **Csh14**. Now, it will be noticed in Fig. 3 that contact **CAd1** is unoperated at the instant involved, because the 2nd memory is free. However, it may happen, as will be seen later on, that the time taken for sending and for recording of the information by the perforator will be considerable as compared with the time taken to record the same information at the "memory" relays. In other words, when the recording by the "memory" relays of the fault wires of the register, the receiver and the marker has ended, some time elapses between that instant and that of the full release of the corresponding memory by the perforator. In order to prevent the holding of the member finder for a relatively long dead time, provision is made to connect the member finder to the second memory while the first completes the sending to the perforator of the information it has recorded.

Relay **CChij** "duplicates" relay **CCabc**, because the number of contacts required to connect the coding wires to the "memory" relays is large. The 29 front contacts **CCh1** . . . **CCh10**, **CCi1** . . . **CCi10**, **CCj1** . . . **CCj9** provide for the connection of the other part of the above-mentioned coding wires to the corresponding "memory" relays.

The closing of front contact **MKa1** prepares the energizing circuit of relay **MKb** and completes the holding circuit of relay **MKa**. It will be noticed that relay **MKb** cannot pull up, its energizing winding being short-circuited through the ground over (1) front contacts **MKa1** and (2) front contacts **CCa4**. Front contacts **MKa3** and **MKa4** are connected in parallel and, upon closing, prepare the general holding circuit of the "memory" relays. The connection in parallel of these contacts is made necessary due to the fact that the number of "memory" relays that can pull up simultaneously and hold over their said contacts is relatively large.

The 21 control wires **Ya0** . . . **Yu0** (Fig. 4) are each associated with a "memory" relay.

Reference to the table of Fig. 9 will show the wiring method used to connect fault wires **Ya0** . . . **Yu0** to the energizing windings of the corresponding "memory" relays. Thus, for example, it will be seen that wire **Ya0** is connected to the winding of "memory" relay **MKm57**, wire **Yb0** to the winding of "memory" relay **MKm59** and wire **Yu0** to the winding of "memory" relay **MKm100**.

Depending upon the polarities applied in register **E** to these various fault wires, a certain number of the above-mentioned "memory" relays pull up and complete a holding circuit for themselves through the closing of their corresponding self-holding contact. These self-holding contacts are shown as a single contact, referenced **MKm1/1**, **MKm104/1**, but actually representing the 104 holding contacts respectively associated with the 104 "memory" relays **MKm1** . . . **MKm104**.

Coding wires **Ca1** . . . **Cb5**, used to send in coded form the number of the faulty register, are connected to the corresponding "memory" relays through the above-mentioned front contacts belonging to relays **CCabc** and **CChij**. Reference to the above-mentioned table will show the wiring method used to connect said coding wires to the corresponding "memory" relays. To explain, it will be found, for example, that coding wire **Ca1** is connected to the energizing winding of relay **MKm6**. The "memory" relays that have just pulled up to record the identity number of the faulty register complete holding circuits for themselves exactly as described before.

A description will now be given of the hunting for, the identification and the connection of the fault wires of the line receiver **R** associated with register **E**. It has been pointed out before that the connection of the fault wires of the register to the control wires of the corresponding "memory" relays was translated into the pulling up of relay **CAf**, this entailing the release of ringing relays **CBdef** and **CBghi**. Owing to the opening of their front contacts **CBd1/10**, **CBel1/10**, **CBf1/6**, **CBg1/10**, **CBh1/10**, **CBi1/6**, relays **CBdef** and **CBghi** definitively break the energizing circuit of magnet **Csh1** and of pilot ringing relay **CAs**, which release.

The release of these relays entails the release of relay **CAd**, owing to the opening of front contact **CSh1/2**.

The release of relay **CAd** causes the release of connecting magnet **Csh14**, owing to the homing of front contact **CAd2**. It will be recalled that the opening of front contact **CAd1** is in operative at the instant under consideration, because connecting magnets **CVa**, **CVd**, **CVc**, as well as relays **CCabc** and **CChij**, hold over holding circuits already described. The release of selecting magnets **Csh1** and **Csh14** prepares the energizing circuit of relays **CAij** and **CAk1** owing to the homing of front-back contacts **Csh1/1** and **Csh14/1**.

When the selecting bars have returned to normal, relay **CAd** releases again. This arrangement thus allows controlling the effective release of the selecting bars that had been used to connect the register to the first memory. It is back contact **CAd3** that provides this control. In effect, the energization of the ringing relay of the receiver is impossible so long as relay **CAd** is pulled up. The closing of this back contact therefore completes the energizing circuit of relay **CCd**, which pulls up: battery, energizing winding of relay **CCd**, back **CAd3**, **CCf1**, front **RHm1**, ground.

Relay **CCd** tells member finder **C** that the faulty register with which it has just being associated is connected to a receiver whose identity will have to be determined and sends the condition of its own fault wires to a memory, this memory further being the same one used to analyze the condition of the fault wires of register **E**.

Through the opening of its back contact **CCd1**, receiver ringing relay **CCd** again removes the short-circuit 75 from the energizing winding of general holding relay

CAab. It is known that relay CAab is slow to release owing to the short-circuiting of its energizing winding. The lag provided is such that the release of this relay will not be effective the instant receiver ringing relay CCd pulls up. The fact that ringing relay CCd pulls up before the release of general holding relay CAab will start in member finder C a new hunting and recording cycle, this time involving the line receiver engaged with register E.

The closing of front contact CCd2 prepares the energizing circuit of connecting magnet CVg. The closing of front contact CCd3 causes the grounding of wire f subsequently to be used for the identification of line receiver R by the energization of the corresponding pilot ringing relay.

Wire f (Fig. 5) is multiplied to all the line and group receivers of the exchange involved. Since each receiver is equipped with a relay such as RHm whose front contact RHm2 connects the corresponding wire f to an identification wire Ia, by analyzing all the wires Ia associated either with the line receivers or with the group receivers of the exchange involved, it will be easy to learn the identity of the calling receiver. In other words, the grounding of the wire Ia corresponding to the calling receiver amounts to bringing this receiver into calling position on the banks of member finder C.

Throughout what follows it will be assumed, by way of example, that the total number of receivers comprised in the exchange involved is 20, this number comprising 10 line receivers and 10 group receivers.

The identification wires Ia associated with the receivers perform the same function as the corresponding wires Ia associated with the aforementioned registers.

Proceeding in the same way as for the registers, a predetermined azimuth is associated with each receiver, be it a line or a group receiver. The first ten azimuths of individual selectors associated with the receivers are reserved for the ten line receivers. The next ten azimuths are reserved for the ten group receivers. Since there are a maximum of ten line receivers and ten group receivers for a 5000-line exchange, it is possible to use a single units-digit to number them. However, it can be arranged to use the member finder for exchanges having more than 5000 lines. In that case, the above single-digit numbering scheme becomes insufficient and requires the use of additional information characterizing the 5000-subscriber group to which the particular line or group receiver involved is connected. It follows from the foregoing comments that the identification of the line or group receivers must be done by means of numbers comprising two digits, the first of them, namely, the tens digit, being reserved to characterize the serial number of a receiver within its group (this digit being comprised, as is known, between 0 and 9), the second digit, namely, the units digit, being reserved to characterize (1) the 5000-subscriber group comprising the receiver involved and (2) the nature of said receiver, that is, to tell whether it is a line receiver or a group receiver. Throughout what follows it will be assumed that the code used for identifying the receivers is as follows:

(1) Units digit zero= line receiver belonging to the first 5000-line group.

(2) Units digit one= line receiver belonging to the second 5000-line group.

(3) Units digit two= group receiver belonging to the first group-selection stage.

(4) Units digit three= group receiver belonging to the second group-selection stage.

Within each group the selectors are numbered in ascending order from digits 0 to 9.

The method of associating the receivers with the various azimuths of the individual selector to which they are connected will now be explained with reference to the table below.

Azimuths	Number of Receiver	Kind
5 1 to 10..... 11 to 20.....	00, 10 : . . . 90 02, 12 : . . . 92	Line—1st 5,000-line group. Group—1st selection stage.

This table shows only the numbers of the line or group receivers involved in the exchange under consideration, that is, the one it was assumed had only 10 line receivers and 10 group receivers to handle the traffic. By referring to this table it can easily be deduced that one line receiver, bearing the number 70, is associated with azimuth 8 and, likewise, that one group receiver, bearing the number 42, is associated with azimuth 15, for example.

The method of hunting for and connecting the calling line receiver will now be explained in the description that follows. It will be assumed that at the instant the fault occurred the calling register, bearing the number 00, was associated with a line receiver bearing the same number. Reference to the above table will show that the corresponding line receiver is associated with an odd azimuth (azimuth 1), with which is associated a selecting magnet bearing the number Csh1. Let it be explained in this connection that the selectors associated with the line and group receivers are mounted on the same multiselector frame as the selectors used for connecting the fault wires of calling registers to the corresponding control wires of the "memory" relays. Let it further be recalled that the identification wires Ia associated with the line or group receivers are distributed the same way as the wires Ia associated with the registers, that is, into 13-wire groups. Of course, since the number of wires Ia is less than 26, the above-mentioned wire groups comprise only 10 wires each, because the total number of receivers associated with the exchange is 20. As is known, these 10-wire groups characterize the even nature of the azimuths at which the corresponding receivers are connected. These wires control pilot ringing relays CA_s and CA_t. Of course, pilot ringing relays CA_u and CA_v are not used, since the number of line and group receivers is less than 26 in the example chosen. From the preceding explanations it follows that the closing of front contact CCd3 completes the energizing circuit of pilot ringing relay CA_s, which pulls up. The pulling up of this relay therefore shows in the member finder that it will be necessary subsequently to energize a selecting magnet corresponding to an azimuth.

The above-mentioned method of hunting for and connecting a receiver, which is wholly similar to the one described with reference to a faulty register, will not be described in detail. Suffice it to recall that selecting magnets Csh1 and Csh14 pull up the instant relay CA_s does so, because the azimuth (azimuth 1) at which the calling receiver is connected is associated with selecting magnet Csh1 and the memory used is the same previously seized upon the connection of the fault wires of register E. However, let it be explained that, in order to prevent any possible mixups between the two memories capable of being associated with member finder C, provisions is made to lock said memories through back contacts CCa1 and CDa1 (Fig. 3). Let it be recalled that the seizing relay (CCabc) of the first memory has completed a holding circuit for itself through the closing of its front contact CCa3. From this it follows that at the instant under consideration and, besides, throughout the holding time of member finder C, back contact CCa1 will remain in open position. The result is that the energization of selecting magnet Csh14 will be prevented throughout the holding time of said finder C, because relay CDabc, the seizing relay of the second memory, will remain unoperated until the release of said finder C, since front contact Csh14/3 will remain in open position.

When the pulling up of selecting magnets Csh1 and Csh14 becomes effective, relay CA_d pulls up again and

through the closing of its front contact CA_{d1} energizes connecting magnet CV_g , associated with the first selector serving the line and group receivers of the exchange involved.

Before proceeding with this description it is well to point out that the number of fault wires that must be connected to the corresponding wires of the "memory" relays is 8 for a line-selecting receiver and 6 for a group-selecting receiver. It has previously been shown that two digits were required to determine the identity of a receiver, whether a line or a group receiver. The determination of its identity therefore requires the use of two contacts per azimuth. Since the maximum number of fault wires to be connected is 8 (for a line-selecting receiver), it follows that it is necessary to provide for the connection of the receivers two individual selectors having, as is known, 8 contacts per assembly, this giving a total of 16 contacts per azimuth for the two selectors together but only 10 of which are used.

The identification of the wipers associated with the contact assemblies of the two selectors mentioned above is done in the same manner described with reference to the register. To explain, let it be pointed out that the wipers belonging to azimuth 1 of these two selectors are referenced $Ca_6 \dots Ch_6$ and $Ca_7 \dots Ch_7$. The connecting magnets controlling the operation of the corresponding selectors are referenced CV_g and CV_h in Fig. 5.

The closing of front contact CA_{d1} therefore completes the energizing circuit of connecting magnet CV_g , which pulls up: battery, righthand winding of magnet CV_g , back CV_{g2} , front CC_{d2} , wire mg across Figs. 5 and 4, front CA_{d1} , back CA_{i1} , ground.

Connecting magnet CV_g completes a holding circuit for itself through the closing of its front contact CV_{g1} : battery, right- and left-hand windings of magnet CV_g in series, front CV_{g1} , ground over general holding wire tg .

The opening of back contact CV_{g2} has no effect at the instant under consideration, connecting magnet CV_g having completed a holding circuit for itself through the closing of its front contact CV_{g1} .

The energizing circuit of connecting magnet CV_h is completed through the closing of front contact CV_{h3} : battery, right-hand winding of selecting magnet CV_h , back CV_{h2} , front CV_{g3} , ground over general holding wire tg .

The closing of front contact CV_{g4} prepares the energizing circuit of relay CC_f . The pulling up of magnet CV_g causes the connection of wipers $Ca_6 \dots Ch_6$ associated with the corresponding selector.

Connecting magnet CV_h completes a holding circuit for itself through the closing of its front contact CV_{h1} : battery, right- and left-hand windings of magnet CV_h in series, front CV_{h1} , ground over general holding wire tg .

The opening of back contact CV_{h2} produces no effect at the instant involved, because connecting magnet CV_h holds through the closing of its above-mentioned front contact CV_{h1} .

The closing of front contact CV_{h3} has the effect of grounding the two verticals corresponding to wipers Ca_6 and Ch_6 .

The closing of front contact CV_{h4} completes the energizing circuit of relay CC_f , which pulls up: battery, relay CC_f , front CV_{h4} and CV_{g4} , ground.

The energizing winding of relay CA_{ab} is short-circuited through the closing of front contact CV_{h5} .

The grounding of wipers Ca_6 and Ch_6 entails the operation of coding relays $CF_a \dots CF_h$, $Cl_a \dots Cl_e$. These coding relays form coding pyramids similar to those previously mentioned in connection with the registers. The first of these pyramids, that is, the one comprising coding relays $CF_a \dots CF_h$, is used to send in coded form to code wires $Cc_1 \dots Cc_5$ the information concerning the tens digit in the number of the re-

ceiver engaged with the register at the instant the fault occurs. Likewise, coding relays $Cl_a \dots Cl_e$, forming the second pyramid, are used to send in coded form to code wires $Cd_1 \dots Cd_5$ the information concerning the units digit in the number of the receiver engaged with the register at the instant the fault occurs. The wiring method used to connect wipers Ca_6 and Ch_6 to identification wires $Cc_1/5$ and $Cd_1/5$ will not be described, the method used being identical with the one described with reference to register E.

When the pulling up of magnets CV_g and CV_h becomes effective, continuity is ensured between the fault wires ($R_a \dots Rh$) of line receiver R and the control wires ($Y_a \dots Yh_1$) of the first memory then engaged with member finder C. Reference to the table of Fig. 9 will show the method used to connect control wires $Y_{a1} \dots Y_{h1}$ and code wires $Cc_1/5$ and $Cd_1/5$ to "memory" relays $MKm_1/104$.

It was pointed out before that the closing of front contact CV_{h5} had caused the short-circuiting of the energizing winding of general holding relay CA_{ab} . As is known, this relay does not release immediately and this lag is used to bring into calling position the other individual members capable of being connected to register E at the instant of the fault.

It is recalled that these individual members are a line receiver and a line marker. The recording of the fault wires of the line receiver having just been effected, the member finder will therefore now proceed to hunt for the line marker engaged with the register. It has been pointed out before that the grounding of wire c (Fig. 4) causes in receiver R and in marker M the energization of ringing relays RH_m and MM_u . However, the pulling up of ringing relay MM_u , associated with line marker M, had no effect, because magnets CV_g and CV_h , being not yet energized, had their front contacts CV_{h4} and CV_{g4} in "open" position and consequently relay CC_f remained unoperated. On the other hand, when the connection of the fault wires of receiver R becomes effective, the pulling up of the pilot ringing relay (CC_e) of the markers can become effective, owing to the energization of relay CC_f .

Relay CC_f is designed to control the connection of the fault wires of receiver R to the corresponding control wires of the "memory" relays of the first memory. The pulling up of relay CC_f will now start (1) the release of the selecting bars previously engaged to connect the receiver and (2) the positioning of the selecting bars that must be used to connect line marker M.

Through the opening of its front contact CC_{f1} , relay CC_f breaks the energizing circuit of relay CC_d , which releases. Through the closing of its front contact CC_{f2} , relay CC_f prepares the energizing circuit of the pilot ringing relay (CC_e) of the markers. The ground applied to wire f , serving to identify the calling receiver, is removed through the opening of back contact CC_{f3} .

The release of relay CC_d has no effect at the instant involved.

The removal of the ground from wire f causes the release of selecting magnet Csh_1 , which had been used before to connect line receiver R. This release entails the opening of front contact $Csh_{1/2}$, the effect of this being to break the energizing circuit of relay CA_d , which releases.

Selecting magnet Csh_1 is released at the same instant as pilot ringing relay CA_s . The release of relay CA_s causes, among other things, the opening of its front contact CA_{s1} , the effect of this being to prevent any untimely energization of relay CA_{ij} upon the release of relay CA_d .

The release of relay CA_d causes the opening of its front contact CA_{d1} , the effect of this being to remove the ground applied to wire mg , thus preventing any untimely energization of a connecting magnet before the corresponding selecting bar is placed in a suitable position.

The opening of back contact $CAd2$ breaks the energizing circuit of selecting magnet $Csh14$, associated with the first memory engaged with member finder C.

Through the closing of its back contact $CAd4$, relay CAd completes the energizing circuit of marker ringing relay CCe : battery, relay CCe , front $CCf2$, back $CAd4$, wire r , front $MMu1$, ground.

It will be noticed that, the same way as previously described with reference to the connection of a receiver R, the pulling up of the marker ringing relay is effected after having controlled the release of the selecting bars previously engaged, this control being effected by back contact $CAd4$ of relay CAd .

The pulling up of marker ringing relay CCe will start the cycle of operations involved in hunting for and connecting the calling line's marker (M). General holding relay $CAab$, whose energizing winding was previously short-circuited through the closing of front contact $CVh5$, has not yet released when marker ringing relay CCe pulls up. The fact the general holding relay $CAab$ has not yet released its armature when relay CCe pulls up, means that register E, which had previously been brought into calling position on the banks of member finder C, is associated (1) with a receiver and (2) with a marker, this requiring the starting of the operations of hunting for and recording the fault wires of said marker M.

Through the opening of its back contact $CCe1$, relay CCe removes the short-circuit from the energizing winding of general holding relay $CAab$. Through the closing of front contact $CCe2$, a ground is applied to wire p to cause the energization of the pilot ringing relay associated with the calling-line marker and of the selecting magnet that is to control the positioning of the corresponding selecting bar at the azimuth of the marker involved. Relay CCe completes a holding circuit for itself through the closing of its front contact $CCe3$: battery, relay CCe , front $CCf2$, $CCe3$, wire r , front $MMu1$ associated with calling marker M, ground.

The energizing circuit of connecting magnet CVi is prepared through the closing of front contact $CCe4$.

Before proceeding with this detailed description of the connection of the fault wires of the calling marker to the corresponding control wires of the "memory" relays, the method will be described as associating the line and group markers of the exchange involved with the corresponding azimuths of the individual selectors of member finder C.

It will be assumed, by way of example, that the exchange involved comprises, for the normal handling of its traffic, a set of 26 markers comprising 20 line and 6 group markers. It will be recalled in this connection that the line or group markers are permanently associated with line-selecting and group-selecting means. Generally two markers are allotted to each line-selecting or group-selecting means. Thus, the above 20 line markers are associated with 20 line-selecting sets. Likewise, the 6 group markers are associated with 3 group-selecting means. It will further be recalled that the capacity of a line-selecting means is 500 subscribers. It follows, therefore, that the 10 line-selecting means mentioned above represent a total capacity of 5000 subscribers.

Within each line-selecting means the associated markers will be referenced marker 1 and marker 2. From this it follows that, in order to determine the full identity of a marker, it is necessary to have the following information:

(1) The 1000 group by which the called subscriber is served.

(2) Within that 1000 group, the identity of the 500 group by which the called subscriber is served. According to the foregoing, two line-selecting means are associated with each 1000 group.

(3) Within a line-selecting means, the number of the marker (marker 1 or marker 2).

These explanations will now allow explaining the method of associating the line markers with the corresponding azimuths of the selectors that are to connect their fault wires to the control wires of the corresponding "memory" relays.

The markers are grouped in the ascending order of the 1000's. Within each 1000, the numbers of the line-selecting means themselves are grouped in ascending order. Likewise, within a line-selecting means, the two markers mentioned above are grouped in the following order: marker 1 and marker 2. From this it follows that each 1000 has four azimuths at which are associated the four markers serving the two line-selecting means making up the corresponding 1000. To explain, with azimuth 1 is associated the first marker of the first line-selecting means serving the first 1000. Likewise, with azimuth 2 is associated the second marker serving the first line-selecting means of the first 1000, and so forth.

To complete these explanations reference will be made to the table below, giving, for the whole exchange, the association of the 20 azimuths with the corresponding 20 line markers.

Azimuth	Marker Number	1000's Number	Line-Selecting Means Number
1	1	0	0
2	2	0	0
3	1	0	1
4	2	0	1
-----	-----	-----	-----
17	1	4	0
18	2	4	0
19	1	4	1
20	2	4	1

The method of associating the azimuths of the selectors with the corresponding group markers will now be described in identical fashion. It is necessary to determine two elements in order to learn the full identity of a group marker:

(1) The identity of the group-selecting means with which the marker involved is associated.

(2) The serial number of the marker in the group-selecting means. In harmony with the line markers, the two markers associated with a group-selecting means will be designated "marker 1" and "marker 2."

The corresponding 6 azimuths are associated with the 6 group markers in the ascending order of the corresponding serial numbers of the group-selecting means and the corresponding serial numbers of the group markers in said group-selecting means.

The table below shows the relationship existing between (1) the azimuths of the individual selectors associated with the group markers and the serial numbers of the group-selecting means and (2) the serial numbers of the group markers in said group-selecting means.

Azimuth	Group-Selecting Means Number	Group Marker Number
21	0	1
22	0	2
23	1	1
24	1	2
25	2	1
26	2	2

The detailed description will now be resumed of the operations leading to the connection of the fault wires of line marker M to the corresponding control wires of the "memory" relays of the first memory. It will be assumed by way of example that at the instant of the

fault the register is associated with a line marker forming part of the first line-selecting means serving the first 1000-subscriber group of the exchange involved. It will further be assumed that in that line-selecting means the marker associated with the register bears the number 1. Reference to a previously-mentioned table will show that the marker M here involved is connected at azimuth 1 of the individual selectors that must make the connection of said marker to the corresponding "memory" relays.

An identification wire *s* is associated with each marker such as M. For the exchange involved, there are therefore a total of 26 wires *s*, which can be divided into two groups, one comprising 20 wires associated with the 20 line markers and the other one 6 wires associated with the 6 group markers. These wires are grouped into cable I, previously mentioned and terminating, as is known, (1) at pilot ringing relays CAs—CA_t and (2) at selecting magnets Csb1 . . . Csh13. The method of associating these wires with the corresponding selecting magnets will not be described again. But it will be recalled, by way of example, that the wire *s* associated with the marker corresponding to azimuth 1 controls selecting magnet Csh1 and that the wire *s* associated with the marker corresponding to azimuth 26 controls selecting magnet Csh13.

It follows from the foregoing that the marker associated with register E must cause through its wire *s* the energization of pilot ringing relay CAs. The energization of this relay is in fact determined by the closing of front contact CCe2, which grounds wire *p*. As examination of Fig. 6 will show, this wire *p* is multiplied to all the 26 front contacts MMu2 associated with the 26 line and group markers. As is known, the energization of relay CAs entails, through the closing of its front contact CAs1, the energization of relay Ca1, which itself causes, through the closing of its front contact Ca1, the energization of selecting magnet Csh1, associated with the azimuth 1 corresponding to the line marker associated with the faulty register. Further, selecting magnet Csh14, associated with the first memory, pulls up in accordance with a method already described.

When the energization of selecting magnets Csh1 and Csh14 becomes effective, or, what amounts to the same, when the selecting bars and the corresponding clutches are in suitable position, relay CAD pulls up again, owing to the closing of front contacts Csh1/2 and Csh14/2.

Relay CAii, associated with the first memory, releases again, owing to the placing in operation position of front-back contact CAD2. It follows from this that the energizing circuit of connecting magnet CVi is completed over the following circuit: battery, right-hand winding of magnet CVi, back CVi2, front CCe4, wire mg across Figs. 6, 5 and 4, front CAD1, back CAi1, CAk1, ground.

Selecting magnet CVi is associated with the individual selector whose wipers are referenced Ca8, Ch8 in Fig. 6. As examination of that figure will show, this selector is associated with the line and group markers to connect their fault wires to the control wires of the corresponding "memory" relays. However, since the number of fault wires of the line and the group markers is 10 and 8, respectively, it follows that it is necessary, in order to connect all the fault wires associated either with a line or with a group marker, to provide two individual selectors per azimuth or, what amounts to the same, per marker. The second individual selector in question has its wipers referenced Ca9 . . . Ch9 in Fig. 6 and is associated with connecting magnet CVj. Connecting magnet CVi completes a holding circuit for itself through the closing of its front contact CVi1; battery, right- and left-hand windings of magnet CVi in series, front CVi1, ground on general holding wire *tg*.

The opening of back contact CVi2 has no effect at the instant under consideration, connecting magnet CVi having just completed a holding circuit for itself through the closing of its front contact CVi1. The closing of

front contact CVi3 completes the energizing circuit of connecting magnet CVj, which pulls up: battery, right-hand winding of magnet CVj, back CVj2, front CVi3, ground on general holding wire *tg*.

Ground is applied to wipers Ca8, Ch8 through the closing of front contact CVi4. A ground is applied to wire *t* to tell the perforator subsequently that it must record the fault wires belonging to a marker.

Connecting magnet CVj connects wipers Ca9 . . . Ch9. Through the closing of its front contact CVj1 it completes a holding circuit for itself over the following circuit: battery, right- and left-hand windings of magnet CVj in series, front CVj1, ground on general holding wire *tg*.

The opening of back contact CVj2 has no effect at the instant under consideration, connecting magnet CVj having just completed a holding circuit for itself through the closing of its front contact CVj1. Through the closing of front contacts CVj3, CVj4, CVj5, grounds are sent over wires x1, y1, z1 to allow identification of the fifties-selector frame, the final-selector frame and the overflow split frame engaged at the instant of the fault. Finally, the energizing winding of general holding relay CAab is short-circuited through the closing of front contact CVj6 to cause the subsequent release of member finder C.

It will be recalled that the line and the group markers have 10 and 8 fault wires, respectively. These wires are referenced Sa . . . Sh/Sj in Fig. 6.

This showing has been used to allow showing at the same time the 10 wires Sa . . . Sj associated with a line marker or the 8 wires Sa . . . Sh associated with a group marker.

The energization of connecting magnets CVi and CVj causes the operation of the corresponding selectors, this having the effect of connecting the 10 fault wires Sa . . . Sj of line marker M to the control wires Ya2 . . . Yj2 of the corresponding "memory" relays.

It has just been pointed out that the closing of front contacts CVj3, CVj4, CVj5 had the effect of grounding wires x1, y1, z1. The use of these wires, whose function, as has been pointed out, is to allow identification, if need be, of a fifties-selector frame, a final-selector frame or, finally, an overflow split frame, will be described in what follows.

It is known that in the course of the line-selecting operations the seized line marker controls the routing of the call from the line-selecting means by marking in succession (1) a fifties selector and (2) a final selector. It will be recalled that in a telephone system using crossbar switches, such as the system to which reference has been made in this description, the subscribers are grouped by fifties, the association of ten fifties constituting what is called a line-selecting means having capacity for 500 subscribers.

Whenever in the course of putting through a call, and more particularly in the course of the line-selecting operations, the register reveals that the time taken to perform such an operation is abnormally long, it is not necessarily the fault either of the seized common member (register) or of the individual members associated therewith, that is, the line receiver and the line marker, in the example here chosen. The putting through of the call is indeed dependent on the proper operation not alone of the common and the individual members but also of the selector frames that normally must be used for putting through said call. Thus it is, for example, that an abnormally-long holding time of the marker does not necessarily mean that the marker involved is faulty but that the selector frames to which it is connected may themselves not be operating properly. In the case of the line selection, line marker M is associated, as is known, (1) with a fifties-selector frame and (2) with a final-selector frame. Further, if all the fifties selectors of a split having access to the final selector by which the subscriber is served

are busy, the call can still be put through by using an overflow selector giving access to some other fifties-selector split having access to the final selector by which the above-mentioned subscriber is served. It is therefore important that in the course of the operations involved in recording the fault wires of a line marker there be identification of the fifties-selector frames, final-selector frames and overflow-selector frames engaged with the marker at the instant the fault occurs.

An identification contact has been provided in each of the above-mentioned frames. These contacts are referenced t_1 , t_2 , t_3 in Fig. 6, being respectively the identification contacts of the fifties-selector, final-selector and overflow-selector frames. The method of identification is similar to the one described with reference to the identification of register E, for example.

It will be assumed throughout what follows that each line-selecting means comprises 4 fifties-selector splits. Likewise, it will be assumed that there are also four splits of three first-selector frames each in each group-selecting means. From this it follows that each marker can have access either to 12 fifties selectors, in the case of a line-selecting means, or to 12 first selectors, in the case of a group-selecting means.

As reference to Fig. 6 will show, each wire x_1 belonging to a predetermined marker (be it a line or a group marker) is multiplied to 12 identification contacts t_2 corresponding either to the 12 fifties-selector frames or to the 12 first-selector frames. Each contact t_2 has an identification wire. These wires are referenced $G_0/11$ for the whole 12 fifties or first selectors of a line- or a group-selecting means. It was pointed out before that the total number of markers associated with a 5000-line exchange was 26, namely, 20 line markers and 6 group markers. Since each marker has one wiper, such as Cc_8 , 26 wires x_1 are associated with each selector. Since each marker will always have access to twelve quite-definite fifties-selector frames, in order to determine the full identity of a fifties-selector frame it suffices to know simply the serial number of this frame in the line-selecting means to which it is connected. As pointed out before, the identity of this line-selecting means is recorded, for it allows determining the identity of the marker engaged with the register at the instant of the fault. In other words, the fifties-selector or the first-selector frames can have similar identification numbers in the various line-selecting or group-selecting means, because the identity of the corresponding line-selecting or group-selecting means allows learning the full identity of the corresponding markers. Thus, 12 identification wires $G_0 \dots G_{11}$ are sufficient to provide identification of all the fifties-selector or first-selector frames of the exchange involved. Stated otherwise, in the cable referenced $G_0/11$, $H_0/9$, $I_0/3$, each group of 12 wires $G_0/11$, $H_0/9$, $I_0/3$ is multiplied on its own to the whole 26 corresponding wipers, namely, Cc_8 , Cd_8 , Ce_8 .

Also, it will be assumed that a line or a group marker can have access either to 10 final selectors or to 10 second selectors; accordingly, the identification wire y_1 associated with a predetermined marker is multiplied to the whole 10 contacts t_1 corresponding either to the 10 final selectors or to the 10 second selectors associated with the corresponding line-selecting or group-selecting means.

Finally, each line marker can have access to 4 overflow-selector frames, this requiring, as reference to the figure will show, the multiplying of wire z_1 to the whole 4 identification contacts t_3 , each belonging to a predetermined overflow-selector frame.

Identification wires $G_0/11$, $H_0/9$, $I_0/3$ have access respectively to three coding-relay groups CLa/i , CLa/h and CHg/i . The operation of these coding pyramids will not be described, having already been explained. However, it is well to point out, with reference to the sending in coded form of the information relative to the identification number of the finders, the fifties selectors or the first-

selector frames, that the numbers to be sent are comprised between 0 and 11, this corresponding to 12 different signals. Since with the code previously used it is possible to send only 10 different signals, an additional coding relay (CLi) has been provided, charged with sending, if needed, through the closing of its front contact $CLi1$, a ground over additional coding wire Ce_6 . As will be seen later on, wire Ce_6 allows direct control of the perforator's punching for the previously-mentioned line 11. At the same time that this additional punching is done, the units digit is sent in code the same way as before. To explain, if the number to be sent is 11, for example, the digit 1 is sent in the standard coded form (ground on wires Ce_1 , Ce_5) and wire Ce_6 is grounded. As will be seen later on, this results in the punching of two holes in the proper column of the recording form, one hole as a result of the sending of the code for digit 1 and one hole representing the grounding of wire Ce_6 , this hole, as is known, being made on line 11. It is possible in this way to send 20 different perforations by punching an additional hole. By also using a perforation on line 12 of the recording form, it is possible to send 20 different indications per column.

The method of identifying the markers will now be explained. As pointed out before, the line markers are grouped (1) in the ascending order of the serial numbers of the line-selecting means and (2) in the ascending order of the 1000's to which the ten line-selecting means are connected. It will further be recalled that in the line-selecting means the two associated markers are each assigned a number and are grouped in the following order: marker 1, marker 2.

Four relays, referenced CHa , CHd , CHe , CHf and operating as follows, are provided for identification of the markers. Relay CHd and CHe are designed to identify the two markers associated either with a line-selecting or with a group-selecting means. The method of associating the markers with the corresponding relays is as follows:

- (1) Relay CHd =marker 1 in the first or second 500-line group.
- (2) Relay CHe =marker 2 in the first or second 500-line group.
- (3) Relay CHa =first 500-line group.
- (4) Relay CHf =second 500-line group.

Figs. 6 and 7 do not show in detail the method of connecting the wipers associated with the line and group markers to the corresponding identification relays. These wiring methods can be very easily deduced from the foregoing explanations; for example, the marker associated with azimuth 1 forms part, as is known, of the first 500-subscriber group and bears the number 1 in said group, its corresponding identification wiper, namely, wiper Cb_8 , being connected, by means of wire Sa through cable S, to the left-hand winding of relay CHd . Likewise, the wiper corresponding to azimuth 2 is connected by means of wire Sb to the left-hand winding of relay CHe , and so forth. Relays CHd and CHe energize in series with relays CHa and CHf , with the result that, for each wiper whose connection becomes effective owing to the operation of the corresponding selector, two identification relays pull up. The method just explained applies as well to the line and the group markers.

As regards a line marker, it is necessary to give in addition the serial number of the 1000's to which it is connected or, more exactly, to which is connected the line-selecting means with which it is associated. Identification of the 1000's is done through wipers Ca_8 , which can be associated through wires $S0/4$ with identification relays $CEf \dots CEi$. The wiring method used is as follows. The first four azimuths, which, as is known, are assigned to the first 1000's, have their corresponding wipers Ca_8 connected by means of wire $S0$, through cable S, to the energizing winding of coding relay CEi . Likewise, the next four azimuths are connected electrically to the energizing winding of coding relay CEf .

by means of wire S_1 , and so forth. The coded information concerning the identity of the fifties-selector, final-selector and overflow-selector frames, as well as the information concerning the identity of the marker seized, is sent through cable C to the corresponding "memory" relays.

At present, the "memory" relays of the first memory have therefore just recorded the identity of the marker associated with register E, the condition of its fault wires $S_a \dots S_j$ and the identity of the various above-mentioned selector frames with which it was engaged.

It was pointed out before that the energizing winding of general holding relay $CAab$ was short-circuited owing to the closing of front contact CVj_6 associated with connecting magnet CVj . At present, the recording of the fault wires of the various individual members engaged with register E, namely, receiver R and marker M, has therefore just become effective. Since there are no other individual members capable of being engaged with the register, the release of the member finder will therefore be able to take place through the slow release of general holding relay $CAab$. It is known that holding relay $CAab$ releases with a certain lag, due to the short-circuiting of its energizing winding.

Through the opening of its front contact CAb_2 , holding relay $CAab$ removes the ground from general holding wire tg , this bringing about the release of all the connecting magnets $CVa \dots CVj$. Relay CCf , having its energizing winding broken owing to the opening of front contacts CVg_4 and CVh_4 , releases, this entailing the release of marker ringing relay CCe . Through the opening of its front contact CCe_2 , relay CCe removes the ground from identification wire p , this entailing the release of selecting magnet Csh_1 and of relay CAd owing to the opening of front contact $Csh_1/2$. This relay in turn causes the release of connecting magnet Csh_{14} owing to the return to normal of front-back contact CAd_2 .

Further, the removal of the ground from general holding wire tg causes the release of relays $CCabc$ and $CCchj$, which served (1) to seize the first memory and (2) to provide metallic continuity between code wires $Ca_1 \dots C_{16}$ through the closing of their front contacts referenced $CCa_5 \dots CCj_9$ in Fig. 5. The opening of said front contacts has no effect at the instant under consideration, since the "memory" relays hold over their respective holding contact, as has already been pointed out.

The opening of front contact CCa_4 removes the ground from wire m , this entailing the pulling up of relay MKb , while relay MKa holds in series with said relay MKb : battery, relay MKa , back MKd_2 , relay MKb , front MKa_1 , ground.

The pulling up of relay MKb entails the pulling up of the busying relay (MKe) of the first memory, owing to the closing of front contact MKb_1 : battery, relay MKe , front MKb_1 , ground.

It will be assumed in what follows that only one perforator is provided to record information concerning the various faults likely to develop in the common and individual members of the exchange. Since there are two memories capable of being connected to said perforator, a connector K is provided to connect said memories to perforator P. A test relay in connector K is associated with each memory. These relays are referenced KCt and KCt' in Fig. 8 and they are respectively associated with the first and the second memory.

With each test relay KCt and KCt' is associated a front contact MKb_2 , only one of which, the one belonging to the first memory, is shown in Fig. 8. The closing of this contact brings the first memory into calling position on the banks of connector K. Relay KCt therefore pulls up: battery, front PD_1 , back KCa_1 , left-hand winding of relay KCt , front MKb_2 , ground.

It is well to explain that front contact PD_1 is closed, because relay PD_1 , with which it is associated, shows the

availability of the perforator and characterizes its availability by pulling up.

The energization of test relay KCt tells perforator P that the calling memory is memory 1. Relay KCt and KCt' form a relay chain whose operation is well known.

Relay KCt completes a holding circuit for itself through the closing of its front contact KCt_1 , which further entails the energization of relays KCa and $PDno$: battery, windings of relays $PDno$ and KCa in series, back KCt_1 , front KCt_1 , right-hand winding of relay K, ground over a circuit already described.

Through the closing of its front contact KCt_2 , relay KCt prepares the energizing circuit of relay MKc . The energization of relay MKe busies the first memory, through the opening of back contact MKe_1 . It will be recalled in this connection that the availability of the memories is characterized by the presence of ground on wires Aa and Ab (Fig. 8). The closing of front contact MKe_2 prepares a holding circuit for relay MKd .

20 Perforator P forms no part of the invention but it is of a type currently used in mechanical recording. To understand the specification it is nevertheless necessary to describe its members, enclosed in a dotted-line box referenced P in Fig. 8. The perforator comprises 12

25 punches, intended to make perforations on lines 0 . . . 12 of the recording forms. The control of the punches is effected in two cycles. With each of them is associated a clutch, controlled by an auxiliary magnet. Stated otherwise, there are as many auxiliary magnets as

30 there are punches to be controlled. The energization of an auxiliary relay places the corresponding clutch in operating position, without however causing the operation of the punch. The operation of the corresponding punch is then caused by energizing a magnet, a so-called "perforating" magnet, common to all the punches. This arrangement therefore allows causing the operation of one or more punches simply by energizing that magnet, the operation depending on whether the auxiliary magnets of the corresponding punches are energized or not.

35 The recording form is moved by a carriage bearing a brush Pk that moves in front of 80 stationary position terminals and that accordingly can open or close 80 different electrical circuits. There is a specific column in the recording form for each terminal. These terminals are referenced $Pp_1 \dots Pp_{80}$ in Fig. 8.

40 It was pointed out before that 40 columns in the recording form were sufficient to record all the faults likely to affect either the common or the individual members of the exchange involved. Therefore, the above-mentioned identification terminals can be multiplied two by two. The 80 identification terminals are thus actually associated, in this particular embodiment, with 40 electrical circuits, the multiplying having been so done that terminal 1 will be connected to terminal 41, terminal

55 2 to terminal 42 and, finally, terminal 40 to terminal 80. With each 2-terminal group is associated a so-called "column" relay, whose role will be explained later. These relays, 40 in number, are referenced $PAa \dots PA_1$, $PB_1 \dots PBt$ in Fig. 8 but they are shown as a single relay, referenced PAa/t , PB_1/t . These relays are connected in the order $PAa \dots PA_1$, $PB_1 \dots PBt$ to the 40 pairs of position terminals 1 and 41 . . . 20 and

60 21 and 61 . . . 40 and 80 by means of the 40 position wires $p_1 \dots p_{20}$, $p_{21} \dots p_{40}$ associated with the energizing windings of the corresponding 40 column relays.

65 It was pointed out before that the energization of relay KCt had entailed the energization of relay $PDno$ owing to the closing of front contact KCt_1 . Relay $PDno$ characterizes the seizure of the perforator. Through the closing of its front contact PDn_2 , relay $PDno$ prepares a holding circuit for relays PCo , PCp , PCq . The energizing circuit of memory-connecting relay MKc is completed through the closing of front contact PDn_3 : battery, relay MKc , front KCt_2 , PDn_3 , ground.

The energizing circuit of column-relay controlling relay PC_m is completed through the closing of front contact PD_{n4} : battery, relay PC_m , back PC_{l1} , PC_{k3} , PC_{j4} , PC_{i4} , PC_{h7} , PC_{g7} , PC_{f7} , PC_{e7} , PC_{d7} , front PD_{n4} , back PD_{l1} , back Ceh , ground.

Contact Ceh is a contact charged with controlling the step-by-step advance of the recording form. This step-by-step advance is actually provided by a ratchet wheel that occupies such a position that the pawl at the end of contact Ceh falls into the space between two teeth of said ratchet wheel when the recording form is stopped in a position corresponding to the punching of a predetermined column.

Relay MK_c is intended to connect "memory" relays $MK_{m1}/104$ to perforator P . In view of the large number of wires that must be connected, namely, 104 in the example chosen, a single relay is obviously insufficient. Therefore, relay MK_c actually consists of a certain number of independent relays, whose windings are all connected in parallel and whose front contacts are suitably distributed in order to connect the above-mentioned 104 wires. To simplify, relays MK_c are shown as a single relay in Fig. 8. The multiplying arrow immediately below the lower outlet of the energizing winding of relay MK_c characterizes the fact that relay MK_c actually consists of a certain number of elementary relays all operating at the same time and all performing the same function. The 104 front contacts used to connect the 104 "memory" relays $MK_{m1}/104$ to the perforator's 104 control wires $r1/104$ are shown as a single front contact $MK_{c1}/104$ in Fig. 8.

The closing of front contact $MK_{c1}/104$ completes a holding circuit for the first memory's busying relay MK_e : battery, relay MK_e , front $MK_{c1}/104$, ground.

Relay PC_m completes a holding circuit for itself through the closing of its front contact PC_{m1} : battery, relay PC_m , front PC_{m1} , ground over a circuit already described.

Through the closing of front contact PC_{m2} , a ground is applied to carriage brush P_k : ground, front PC_{m2} , brush P_k .

Seven decoding relays, referenced $PC_d \dots PC_j$ in Fig. 8, are provided to decode the information received by the perforator. These relays are intended to control, over their corresponding contacts, the auxiliary clutch magnets of the above-discussed punch magnets. These punch magnets are referenced $P0 \dots P12$ in Fig. 8.

To punch a hole in a recording form it is necessary to know two things: (1) the number of the column and (2) the number of the line at whose intersection the hole must be punched. The punching of a hole on any of the lines $0 \dots 9$ requires the energization of two of the decoding magnets $PC_d \dots PC_h$. These magnets correspond to the first five elements of the information-sending code mentioned before with reference to the coding of the identity number of the faulty register and of the individual members associated with it. For example, if it is desired to punch a hole on line 2, it is known from a previously-mentioned table that the sending of the digit 2 in coded form requires the use of elements 2 and 5 of the code. Decoding relays PC_e and PC_h correspond to these elements.

Through the closing of their front contacts PE_{e3} and PC_{h4} , decoding relays PC_e and PC_h control, as shown, punch magnet $P2$ (not taking into account the energization of relay PC_m). The control of all the punch magnets, $P0 \dots P9$, is effected the same way just described with reference to the control of punch magnet $P2$. To punch a hole it is necessary not alone to control the corresponding punch magnet but to take into account the position occupied by the recording form before energizing the above-mentioned perforating magnet.

The control of decoding relays $PC_d \dots PC_j$ must therefore depend on the position occupied by the recording form. This control is provided by the 40 column

5 relays PAa/t , PB_a/t mentioned before. For each position occupied by the recording form, brush P_k takes a specific position in front of identification terminals $Pp_1 \dots Pp_{80}$. For each position taken by brush P_k , 10 one of the 40 column relays mentioned above is energized. Thus, for example, reference to Fig. 8 will show that if the recording form occupies the position corresponding to the punching of its first column, brush P_k takes the position corresponding to terminal Pp_1 and thereby closes the energizing circuit of column relay PAa , which then pulls up. In proportion as the recording form advances in the machine, column relays PAa/t , PB_a/t pull up in succession and in the order PAa , $PBb \dots PAt$, PB_a , $PBb \dots PBt$.

15 It was pointed out before that in order to provide the control of an auxiliary punch magnet, it was necessary to control the pulling up of two of the five decoding relays $PC_d \dots PC_h$.

When perforations 20 11 and 12 of the recording form, the corresponding punch magnets are controlled through the two additional decoding relays, PC_i and PC_j . Actually, relays PC_i and PC_j are not decoding relays, because they can control punch magnets $P11$ and $P12$ directly through their 25 front contacts PC_{i3} and PC_{j3} . They constitute a sort of auxiliary relays, because, in order to control one or the other of punch magnets $P11$ and $P12$, it suffices to energize one or the other of relays PC_i and PC_j , which are associated with them.

30 In the description that follows, a full explanation will be given of the role played by relays PC_i and PC_j upon the recording of information concerning, for example, the number of the final-selector frames engaged with marker M .

35 Each of the upper ends of the energizing windings of decoding relays $PC_d \dots PC_j$ is multiplied to a certain number of front contacts of the various column relays, PAa/t , PB_a/t , in order to allow the energization of decoding relays $PC_d \dots PC_j$ at the proper time.

40 To make these explanations clear, the method will be discussed, for example, of recording the number of the register E that had shown up as faulty on the banks of member finder C . It will be recalled that the number of this register is 00. In the course of the preceding description it has been pointed out that this number was recorded in columns 8 and 9 of the recording form, column 8 being used for the tens digit and column 9 for the units digit. On the basis of the foregoing assumptions, the recording form will have two perforations on line 0, one in column 8 and the other in column 9. Of course, no attention is paid here to all the other perforations that must be made in order to record the hour, the number of the receiver, the number of the marker, etc.

45 The sending of digit 0 in coded form requires, as is known, the use of code elements 2 and 4, as examination of a table mentioned before in this connection will show. The sending of the register's number is done by using the whole set of code wires $Ca_1 \dots Ca_5$, $Cb_1 \dots Cb_5$. It follows from the foregoing comments that wires Ca_2 , Ca_4 , Cb_2 , Cb_4 are grounded after the recording in coded form of the register's number. These wires terminate through cable C and front contacts $CC_{a5} \dots CC_{j9}$ at "memory" relays MK_{m2} , MK_{m4} , MK_{m7} , MK_{m9} , corresponding to the above code wires. It will be recalled that the table of Fig. 9 allows seeing the association of "memory" relays $MK_{m1}/104$ with the corresponding control wires. The punching of digit 0 requires the energization of decoding magnets PC_e and PC_g . To punch digit 0 in column 8 and 9 it is thus necessary to connect decoding relays PC_e and PC_g to "memory" relays MK_{m2} and MK_{m4} , to punch column 8, and then to "memory" relays MK_{m7} and MK_{m9} , to punch column 9. This connection of the decoding relays to the corresponding "memory" relays is made through the action of the contacts of the column relays associated with columns 8 and

9, namely, relays PAh and PAi. As is known, one control wire of the perforator is associated with each "memory" relay. These wires are referenced r1/104. Since "memory" relays MKm2, MKm4, MKm7, MKm9 are energized to record the number (00) of the calling register, perforator control wires r2, r4, r7, r9 are grounded over the following circuits:

- (1) Wire r2—front contacts MKc2, MKm2/1, MKa3/4, ground.
- (2) Wire r4—front contacts MKc4, MKm4/1, MKa3/4, ground.
- (3) Wire r7—front contacts MKc7, MKm7/1, MKa3/4, ground.
- (4) Wire r9—front contacts MKc9, MKm9/1, MKa3/4, ground.

The front contacts of column relays PAh and PAi are used to connect wires r2, r4, r7, r9 to decoding relays PCe and PCg. The pulling up of relay PAh, for example, connects wires r2, r4 to decoding relays PCe and PCg, while the pulling up of relay PAi connects wires r7, r9 to the same decoding relays, since the register's number is made up of two identical digits (00).

Each column relay controls 8 front contacts, 7 of them being used to connect, if need be, the energizing windings of the decoding relays to the corresponding "memory" relays, the eighth serving to control relay PC1, which is used to skip unused columns. These front contacts are shown in Fig. 8 as follows. Above the energizing winding of each of the decoding relays, PCd . . . PCj, is shown a single front contact actually representing the 40 front contacts belonging to the 40 column relays, PAa/t and PBa/t. However, it is well to point out that the 40 column relays mentioned above are not necessarily wired, for the reason that, depending upon operating requirements, a predetermined punch magnet need not be used for all the columns of the recording form. In other words, the digit 2, for example, the method of recording which has been discussed before, may be used in a certain number of columns, while different digits may be punched in other columns. A multiplying arrow is used to characterize the 40 front contacts that can operate a specific decoding relay. These contacts are referenced in simplified fashion. Thus, shown for the first decoding relay (PCd) is the reference of the first contact associated with column relay 1 and the reference of the 1st contact associated with column relay 40, etc.

The table of Fig. 10 allows determining the wiring used for each column relay. This table is in two parts. It comprises 40 columns and 9 lines. The columns are numbered 1 to 40 and they correspond to the columns 1 to 40 of the recording form. To explain, it should be pointed out that owing to the multiplying of the perforator's terminals, columns 1 to 40 and 41 to 80 are associated by twos, viz: 1 with 41, 2 with 42 . . . 40 with 80. The first 7 lines belong to the 7 decoding relays of the perforator, that is, to relays PCd . . . PCj. The role of the 8th and 9th lines will be explained later. The association of the 40 columns and the first 7 lines allows making up 280 boxes, corresponding to the $40 \times 7 = 280$ front contacts of the 40 column relays PAa/t and PBa/t. The 80 boxes formed by the intersection of the 40 columns and lines 8 and 9 correspond to the $40 \times 2 = 80$ front contacts of the 40 column relays mentioned above and whose role will be explained later. As pointed out before, the first 7 front contacts of a column relay are not necessarily wired. The purpose of this table is (1) to allow determining the identity of the contacts that have been wired and (2) to show the relationship existing between the wired contacts and the corresponding "memory" relays. When a front contact belonging to any of the column relays PAa/t, PBa/t is not wired, its box contains no information. On the other hand, when one of said front contacts is connected to any of the 104 "memory" relays MKm1/104, its box contains the reference of the associated "memory" relay.

To explain, the method of wiring the contacts of the column relays corresponding to columns 8 and 9 of the recording form will be described with reference to the table. In the course of the foregoing description it was pointed out that the column relays are referenced PAh and PAi. As is known, columns 8 and 9 are used to record the number of the registers of the exchange involved when the latter take the calling position on the banks of the member finder. There being 52 registers all told, the use of lines 11 and 12 of the recording form becomes superfluous, because columns 8 and 9 together allow recording 100 different numbers comprised between 00 and 99. Reference to a previously-mentioned table will show that the "memory" relays used to record the register's number in coded form are referenced MKm1 . . . MKm5, for the recording of the tens digit, and MKm6 . . . MKm10 for the recording of the units digit. Reference to the table of Fig. 10 will show that the first five boxes of column 8 contain the information MKm1 . . . MKm5 and the first five boxes of column 9 the information MKm6 . . . MKm10. This information means that upon energizing column relay PAh (belonging to column 8), the closing of the first five front contacts of said relay, namely, front contacts PAh1 . . . PAh5 (not shown in Fig. 8) connects the five "memory" relays MKm1 . . . MKm5 to the perforator's decoding relays PCd . . . PCh. Similarly, the closing of the first 5 front contacts of relay PHi (belonging to column 9) connects the five "memory" relays MKm6 . . . MKm10 to the 5 decoding relays PCd . . . PCh.

When in advancing in the perforator the recording from successively occupies the positions corresponding to columns 8 and 9, relays PAh and PAi will be energized in succession, thus connecting first the "memory" relays of column 8, and then the "memory" relays of column 9, to the first five decoding relays of the perforator. It will be recalled that the method has already been described of recording the number (00) of the register brought into calling position on the banks of member finder C.

The description will now be resumed of the operation of the perforator as from the moment relay PCm pulls up.

When the recording form reaches a position where column 1 can be punched, contact LCp closes and completes the energizing circuit of relay PDr, which pulls up: battery, right-hand winding of relay PDr, contacts LCp and Ceh in "closed" position, ground.

Through the opening of its front contact PDr1, relay PDr breaks the perforator's availability circuit. Relay PDr completes a holding circuit for itself through the closing of its front contact PDr2: battery, front PDr2, left-hand winding of relay PDr, front PDp1, ground.

Upon the energization of the punch magnets used for punching the first column of the recording form, punching-control contact EC closes and completes the energizing circuit of perforating magnet P: battery, magnet P, contact EC in "closed" position, ground.

Perforating magnet P controls the operation of the punches whose clutches had been placed in operating position by the operation of the corresponding punch magnets.

At the same time that it controls the operation of the punches, perforating magnet P prepares the stepping of a column of the recording form and opens contact Ceh, the effect of this being to break the energizing circuit of relay PCm, which releases, thereby breaking, through the opening of its front contact PCm2, the energizing circuit of column relay PAa, which releases in turn.

The release of column relay PAa causes, through the opening of its contacts PAa1 . . . PAa7, the release of the decoding magnets that had been seized for the punching of the first column. The release of the punch magnets follows from that of the decoding magnets and causes the opening of contact EC, this breaking the ener-

gizing circuit of perforating magnet P. This magnet releases the punches that had been seized and causes the recording form to advance into position for the perforation of column 2. When the recording form has reached position 2, contact Ceh closes again and punching-control relay PCm re-energizes after checking through contacts PCd7, PCe7, PCf7, PCg7, PCh7, PCi7, PCj4 that the decoding magnets that were used to perforate column 1 have actually returned to normal. The pulling up of relay PCm again completes, through the closing of front contact PCm2, the grounding of position brush Pk, the effect of this being to cause the energization of column-2 relay PAb, because brush Pk has just passed into position 2, that is, in front of position terminal Pp2.

The selfsame operation just described is repeated for the perforation of the various other columns of the recording form.

When the recording form reaches the last column, contact CDC closes and causes the release of differential relay PDpq through the energization of its upper winding: battery, contact CDC in "closed" position, upper winding of relay PDpq, ground.

The release of relay PDpq causes the energization of relay MKd through the placing of front-back contact PDp2 in "back" position: battery, relay MKd, front MKc103, back PDp2, ground.

Relay MKd releases the "memory" relays engaged with perforator P. It completes a holding circuit for itself through the closing of its front contact MKd1: battery, relay MKd, front contacts MKd1 and MDe2, ground.

The placing of front-back contact MKd2 in "front" position opens the energizing circuit of relay MKa and short-circuits the energizing circuit of relay MKb, which releases with a certain delay.

Through the opening of its front contacts MKa3/4, relay MKa opens the holding circuit of the "memory" relays, which release in turn.

Relay MKb releases with a certain delay and breaks the holding circuit of relay KCt through the opening of its front contact MKb2.

The release of relay MKc breaks the connection of the "memory" relays to perforator P through the opening of contacts MKc1/104. The opening of front contact MKc107 releases the first memory's busying relay (MKe).

This relay in turn breaks the energizing circuit of release relay MKd through the opening of its front contact MKe2.

Upon the release of relay PDno, back contact PDn1 closes and completes the energizing circuit of PD1m, which pulls up: battery, relay PD1m, back contacts PDn1 and PDp1, ground.

The energization of relay PD1m causes the energization of an electromagnetic clutch (E), the effect being to cause the perforator's carriage to return to normal: battery, clutch E, front PD12, back PDp4, contact CC in back position, ground.

A motor (not shown) then returns the perforator's carriage to normal position. Once this is done, contact CC opens and breaks the energizing circuit of the clutch, which thus disengages the electric motor restoring the perforator's carriage to normal position.

It may be that the recording form contains columns calling for no perforation. In that case, none of the coding relays PCd . . . PCj pulls up when the corresponding column relay energizes. The chain of back contacts PCd1 . . . PCj1 remains closed as a result. The ninth contact of each column relay is designed to make the form skip whenever the column corresponding to the above-mentioned relay is not to contain any perforation. Reference to the table of Fig. 10 will show that the boxes corresponding to the ninth contact of some column relays contain a characteristic sign, in this instance a "ground." The presence of this "ground" means that the corresponding front contact has one of its poles grounded

in Fig. 8. The 40 corresponding front contacts of the 40 column relays TAa/t, TBa/t have their lower poles multiplied together and connected to the chain of back contacts PCd1 . . . PCj1. Thus, upon the energization of the various column relays PAa/t, PBa/t, the above contact chain can be grounded whenever the recording form occupies certain positions.

In other words, the recording form contains columns that must be perforated regardless of the recording effected (case of the recording of the hour, for example) and columns that may or may not be perforated depending upon the particular recording involved. Thus, for example, if the faulty member is a tester, there will be no information in columns 8 and 9, used to record the number of the registers. The column relays corresponding to columns that must necessarily be perforated accordingly have their ninth contact isolated, while the column relays corresponding to columns that may be perforated at option have their ninth contact grounded. Reference to the above-mentioned table will show that the column relays of columns 1 to 7, inclusive, have their ninth contact isolated (the corresponding boxes contain no information), while the relays of columns 8, 9, 10, etc., have their ninth contact grounded, because boxes 1 to 7 must contain perforations regardless of the particular recording involved, while the next columns may or may not be perforated, depending upon what is to be recorded.

From the foregoing explanations it follows that whenever the recording form occupies a position where no perforation is to be made, the chain of back contacts PCd1 . . . PCj1 is grounded, the effect of this being to energize skipping relay PC1. Through the placing of its front-back contact PC11 in "front" position, skipping relay PC1 causes the energization of skipping magnet G: battery, skipping magnet G, front contact PC11, ground over a circuit already described.

Skipping magnet G performs a function identical with that of punch magnets P0 . . . P12. However, it is not associated with any punch, its purpose being to cause a dummy operation of perforating magnet P by causing the closing of the above-mentioned contact EC. In other words, when a column of the recording form is to be skipped, perforating magnet P is energized normally, thus causing the form to advance by one step without however making any perforation, this being achieved thanks to the use of skipping magnet G.

The method of wiring the column magnets of columns 1 to 7, inclusive, will now be described with reference to the table of Fig. 10. As pointed out before, column 1 is used to show the nature of the recording appearing on the recording form. To characterize the recording of a fault occurring in a common or in an individual member of the exchange involved, a perforation is made on line 0 in column 1. It is known that the perforation "0" requires the use of elements 2 and 4 of the five-element code used for sending information from the member finder to the perforator. This perforation therefore calls for the energization of the decoding magnets PCe and PCg corresponding precisely to elements 2 and 4 of said code. The boxes of column 1 corresponding to lines 2 and 4 contain the information MKc105 and MKc106, meaning that the 2nd and 4th front contacts of column magnet PAa are connected through cable R to front contacts MKc105 and MKc106 of relay MKc (it will be recalled that relay MKc actually consists of a certain number of individual relays operating simultaneously). Thus, when the recording form is in position 1 and the corresponding column relay PAa has energized, decoding magnets PCe and PCg have their energizing circuit completed and they pull up in turn.

Columns 2 to 7, inclusive, are intended to record the instant the fault occurs. It will be recalled in this connection that columns 2 and 3 record the day of the month (tens and units), columns 4, 5, 6 and 7 the hour, the

minutes (tens and units) and, finally, tenths of a minute. The information required for this recording is furnished by a clock represented by a rectangle referenced H in Fig. 8. The operation of this clock, which can be mechanical, electrical or of any other type, will not be described. This clock sends the various above-mentioned codes by means of 32 wires referenced *h1/32* in Fig. 8. The first ten of these wires, *h1/10*, are used to send the day-of-the-month code, the first five being used for the tens and the next five for the units. These wires appear in the boxes of lines 1 to 5 in columns 2 and 3. The next seven wires, namely, wires *h1* . . . *h7*, are for sending the hour. Seven wires are used because the figure representing the hour can be comprised between 00 and 23, this requiring the use of perforations on additional lines 11 and 12 of the recording form. It will be recalled that whenever the hour is comprised between 10 and 19, an additional perforation is made on line 11, line 12 being reserved for hours comprised between 20 and 23. Wires *h11* . . . *h17* appear in the boxes of column 4. The last three 5-wire groups, that is, groups *h18/22* . . . *h23/27*, *h28/32*, are for the coded sending of the minutes (tens and units) and of tenths of a minute. These wires are shown in the boxes of columns 5, 6 and 7.

A description will now be given, with reference to the table of Fig. 10, of the method of recording the characteristic potential of the fault wires associated either with the common or with the individual members of the exchange involved. This table shows the method of connecting these fault wires to the corresponding "memory" relays. The corresponding "memory" relays are found again in this table, their identification number being shown in some of the boxes comprised between columns 18 to 39, inclusive. It will be seen, for example, that the 21 boxes of the seventh line of this table (that is, the boxes comprised between columns 19 and 39) belong to the 21 fault wires of the register. As is known, the 7th line of this table is associated with the perforator's decoding relay (PC_i). It will be recalled in this connection that the energization of decoding relay PC_i entails the energization of punch magnet P12, which, as is known, following the energization of perforating magnet P (Fig. 8), provides for recording the information on line 12 of the recording form. Likewise, the boxes of the 6th line of the Fig. 10 table that are comprised between columns 18 and 25, inclusive, belong to the fault wires of the receiver. This 6th line belongs in the perforator to decoding relay PC_i, which controls the punch magnet (P11) subsequently recording on the 11th line of the recording form.

As regards the method of recording the fault wires of the markers, testers and translators, use is made of additional "memory" relays MKm101, MKm102 and MKm103, whose operation will now be described. As regards the markers, for example, it will be noticed that the "memory" relays intended to record their fault wires appear on the second line of the Fig. 10 table, between columns 21 to 31, inclusive. To this second line belongs in the perforator the decoding relay PC_e. It was pointed out before that the first five decoding relays, PC_d . . . PC_h, are used to decode the information sent them in a 5-element code using two elements to send one piece of information. In other words, in order to control from decoding relays PC_d . . . PC_h any punch magnet chosen from among the ten punch magnets P0 . . . P9, it is necessary to energize simultaneously two decoding relays suitably chosen from among the five relays PC_d . . . PC_h. Since the second line of the Fig. 10 table belongs to only one decoding relay (relay PC_e), in order to obtain the operation of any one of the punch magnets P0 . . . P9 it is necessary to energize, through some suitable means, a second decoding magnet suitably chosen from the group PC_d . . . PC_h or, what amounts to the same, to short-circuit the decoding contacts of said relay by means of an auxiliary relay, so as to complete the

energizing circuit of a punch magnet already partly prepared owing to the energization of decoding relay PC_e and the closing of its corresponding front contact.

It has been seen before that lines 11 and 12 of the recording form are reserved (between columns 18 and 19) to record the fault wires associated with the registers and with the receivers. Since at the instant a fault occurs a register can be associated both with a receiver and with a marker, it is necessary to provide for the recording of the marker's fault wires on one of the ten lines 0 . . . 9 still available on the recording form between columns 18 and 39. It will be assumed in what follows that this recording is done on line 2 of the recording form.

Reference to a previously-mentioned table will show that the sending of the digit 2 in coded form requires the use of code elements 2 and 5. It will be recalled that these code elements 2 and 5 correspond in the perforator to decoding relays PC_e and PC_h. When as it advances in the perforator the recording form brings about, through brush P_k, the energization of the column relays belonging to columns 21, 22 . . . 31, decoding relay PC_e will pull up each time a fault must be recorded in predetermined column. In order to make the operation of a punch effective, it is therefore necessary to energize "artificially" the decoding relay corresponding to the missing code element, that is, relay PC_h. An auxiliary relay, referenced PC_o in Fig. 8 and whose front contact PC_{o1} energizes relay PC_h, has been provided to effect this energization.

Relay PC_o can be connected by means of the first front contact of the column-17 relay (relay PA_q) to the auxiliary "memory" relay bearing the number MKm101. The number of this relay appears on the first line of the Fig. 10 table, in column 17. It should be pointed out in this connection that relay PA_q (of column 17) does not have the lower poles of its front contacts PA_{q1} . . . PA_{q9} connected to decoding relays PC_d . . . PC_j. This relay has a special wiring method, because the lower poles of its above-mentioned front contacts are connected to auxiliary relays PC_o . . . PC_q by means of cable R (Fig. 8).

In fact, reference to Fig. 8 will show that the energizing winding of relay PC_o is completed whenever the column-17 relay (PA_q) pulls up: battery, relay PC_o, front PA_{q1}, wire R101 through cable R, front MKc101, MKm101/1, MKa3/4, ground.

The energization of relay PC_o is therefore made dependent upon the energization of "memory" relay MKm101. It was pointed out before that in the course of connecting the marker, the closing of front contact CVi5 (Fig. 6) had the effect of grounding wire t. Wire t is connected by means of cable C, across Figs. 6, 5, 8, and of one of the front contacts CC_{d5} . . . CC_{j9} to the energizing winding of "memory" relay MKm101. Stated otherwise, relay MKm101 pulls up as soon as the connection of the faulty marker becomes effective, because front contact CVi5 is associated with connecting magnet CVi.

It follows from the foregoing explanations that whenever the recording form reaches the positions corresponding to columns 21, 22, etc., as it advances in the perforator, the recording of the fault wires associated with the seized marker will be effected on line 2 of the form.

The recording of the fault wires of the translators and testers of the exchange involved also requires the use of a method similar to the one just described, since line 0 of the recording form is reserved for the translators and line 1 for the testers. For this recording, use is made in the perforator of two auxiliary relays, PC_p and PC_q, associated with two auxiliary "memory" relays, MKm102 and MKm103, the position of whose corresponding boxes will be found in the Fig. 10 table.

In the description of the recording of a fault occurring in a register it has been assumed that the latter was associated with a receiver and with a marker. It may happen that the connection of the receiver to the marker is

not yet effective at the instant the fault occurs. In that case, the markers' ringing relay (CCe—Fig. 6) cannot pull up after the closing of front contact CC_f2 and of back contact CA_d4. Thus, general holding relay CA_{ab}, whose winding was short-circuited upon the connection of the receiver owing to the closing of front contacts CV_h5, will release after a certain lag, since back contact CC_e1 will remain in "closed" position. From this it follows that the release of general holding relay CA_{ab} will entail the release of the member finder and cause, in accordance with a method similar to the one already described, the seizure of perforator P, which then records the same way as previously described.

Also, if the register is not busy with any individual member at the instant a fault occurs, general holding relay CA_{ab}, whose energizing winding has just been short-circuited by the closing of front contact CA_f4, will release after a certain lag, causing the release of the member finder and the seizure of the perforator.

It will now be assumed that, at the instant a fault occurs, register E is connected to a translator D through translator connector CT. It will be recalled that when the connection of the register has become effective, relay CA_f pulls up and wire c is grounded, the effect of this being to cause the energization of relay DA_k, comprised in the translator. This relay DA_k performs a function similar to that of relay RH_m in receiver R. It characterizes the fact that the register with which the translator is engaged has been brought into calling position on the banks of member finder C and that the connection of the member finder has just become effective. Through the closing of its front contact DA_k1, relay DA_k brings translator D into calling position on the banks of the member finder. The method of connecting translator D, which is wholly identical with the method of connecting receiver R, will not be described again. It will be noticed that the front contacts DA_k1 and RH_m1 associated with the ringing relays of translator D and of receiver R are connected in parallel; thus, the closing of one or the other of these contacts causes in member finder C the pulling up of ringing relay CC_d, which therefore, as can be seen, is common both to the receivers and to the translators of the exchange involved. It should be pointed out in this connection that it is in fact possible to use a common ringing relay for the translators and the receivers, because in the exchange referred to in the general description of the operation of the system the register can at no time be connected at once to a translator and to a receiver. Reference to the patent-addition applications mentioned at the beginning of this description will indeed show that, in putting through an outgoing call, the register releases the translator once it has received from the latter the information required for controlling the group selection and thereupon takes the calling position on the banks of receiver connector CR. It follows from these explanations that the same selectors can be used to connect (1) the line and group receivers and (2) the translators. It will be recalled in this connection that the total number of receivers is 20, this number being divided into 10 line receivers and 10 group receivers. Thus, 20 azimuths are occupied on the banks of the selectors associated with the receivers, that is, selectors Ca₆ . . . Ch₆, Ch₇ . . . Ch₇, controlled by connecting magnets CV_g and CV_h.

It will be assumed that the exchange involved has two translators, which will be termed translator 1 and translator 2. It is known that the selectors used to make up a member finder have 26 different azimuths.

Since 20 out of them are used for the 10 line receivers and the 10 group receivers, there are still 6 azimuths left free. It will be assumed that translators 1 and 2 are associated with azimuths 25 and 26. Azimuths 21 . . . 24 thus remain free and can be used to connect additional receivers or translators.

It has been pointed out before that the identification

number of the receivers consists of two digits, the units digit, comprised between 0 and 2, serving to identify the category of the receiver and the tens digit indicating the serial number of the receiver in its category. The determination of the identity of a translator requires knowing only one digit. Since the digits 0, 1, 2 and 3 are used to determine the category of the receivers, six digits, comprised between 4 and 9, are still available for the corresponding column (column 10) of the recording form. Two out of these are used to identify the translators. It will be assumed in what follows that the digits used are digit 4 for translator number 1 and digit 5 for translator number 2.

These digits are recorded in the same column as the digits used to determine the category of the receiver, that is, in column 10 of the recording form. Since the register cannot be connected simultaneously to a receiver and a translator at any time during the selection, the same "memory" relays can be used to record the fault wires of the receivers and the translators. Reference to the Fig. 10 table will show that the "memory" relays used for recording the fault wires of a predetermined member are on one and the same line, further corresponding to the serial number of the corresponding line of the recording form. Thus, without some special trick, the fault wires of the receivers and the translators are recorded on one and the same line, namely, line 11. To overcome this drawback, provision is made to record the fault wires of the translators on line 0 of the recording form. To make this line shift, there is available in the perforator an auxiliary relay referenced PC_p in Fig. 8 and whose function is to direct the energizing ground of punch magnet 4₁ to punch magnet P0. In other words, when as it advances in the perforator the recording form reaches positions 18 and following, the corresponding column relays connect, for each column, the energizing winding of decoding relay PC_i to the corresponding "memory" relay. If, for some predetermined column, decoding relay PC_i must pull up owing to the energization of the corresponding "memory" relay, it completes the circuit of punch magnet P11 through the closing of its front contact PC_i3. On the other hand, when auxiliary relay PC_p is pulled up, its contact PC_p1 switches in the energizing winding of punch magnet P0, owing to the placing of front-back contact PC_p1 in "front" position. From the preceding explanations it follows that, in order to record the fault wires of a translator on line 0 of the recording form, it suffices to energize relay PC_p. Relay PC_p is energized upon the connection of the calling translator as described below.

Since the identification number of the translators comprises only one digit, while that of the receivers comprises two, wipers Ca₆ of the first selector, corresponding to azimuths 25 and 26, with which are associated translators 1 and 2, are left free. This allows using these wipers to energize an auxiliary "memory" relay, referenced MKm102 in Fig. 8, upon the connection of a translator. The energizing circuit of this relay is not shown in Fig. 5. This auxiliary "memory" relay MKm102 appears on line 2, column 17, of the Fig. 10 table. This "memory" relay MKm102, the same way as relay MKm101, energizes column-shifting relay PC_p over the following circuit: battery, relay PC_p, contact PAq2 of the column-17 relay (relay PAq), wire r102 through cable R, front contacts MKc102, MKm102/1, MKa3/4, ground.

In this manner, whenever a translator is brought into calling position, its fault wires are recorded on line 0 of the recording form owing to the consecutive energization of auxiliary "memory" relay MKm102 and of column-shifting relay PC_p.

The operation of the member finder when a tester is brought into calling position will now be described briefly. It will be assumed that the exchange involved comprises 20 testers, divided into ten 2-tester groups,

each corresponding to a line-selecting means serving 500 lines. In other words, with each line-selecting means are associated 2 testers, termed tester 1 and tester 2. The testers are grouped on the azimuths 1 to 20 of individual selector $Ca_{10} \dots Ch_{10}$ the same way as the previously-mentioned line markers. To identify these testers there are 4 identification relays, Ch_b , Ch_c , Ch_a , Ch_f , the first two discriminating the testers in a 500-line group and the last two determining the identity of the 500-line group in a predetermined 1000-line group. It will be noticed that relays Ch_a and Ch_f are common both to the line markers and to the testers. This is due to the fact that whenever a tester is brought into calling position on the banks of the member finder, and at the instant a fault occurs it is associated with a line marker, said marker necessarily forms part of the same 500-line group as the calling tester, since each line-selecting means is associated with two markers and with 2 specific testers. The determination of the 1000's is effected by the set of relays $CE_f \dots CE_j$, which obviously are the same as those serving to determine the 1000's comprising the calling marker. The reason for this is the same as mentioned before in connection with relays Ch_a and Ch_f .

Whenever in hunting for a calling line a tester is brought into calling position on the banks of the member finder, an individual ringing relay, not shown but forming part of tester equipment T, closes its front contacts TFy_1 and TFy_2 (Fig. 7). The effect of this is to energize ringing relay CB_{abc} over the following circuit: battery, relay CB_{abc} , back CAf_5 , CB_9 , front TFy_1 , ground.

Through the opening of its back contact CB_{a1} , relay CB_{abc} breaks the register's ringing circuit and through the closing of its front contact CB_{a2} prepares the energizing circuit of connecting magnet CV_k , which brings about the operation of selector $Ca_{10} \dots Ch_{10}$. The energizing circuit of general holding relay CA_{ab} is completed by the closing of front contact CA_{b3} : battery, resistance CR_{54} , relay CA_{ab} , front CA_{b3} , ground.

As from this moment, the method of hunting for and connecting a calling tester is the same as described with reference to a calling register, already discussed. When the hunting for the tester has ended, connecting magnet CV_k pulls up and connects the tester's fault wires to the corresponding "memory" relays. It further prepares, through the closing of its front contact CV_{k4} , the energizing circuit of marker ringing relay CC_e . If a line marker is then engaged with the corresponding tester, relay MM_u of the corresponding marker pulls up, owing to the grounding of wire j by front contact CV_{k6} through selector Cc_{10} . The hunting for and the connection of the marker are then effected the same way as previously described with reference to the line marker M associated with register E.

Since in hunting for the calling line only one line receiver and one line marker are used as common and individual members, the "memory" relays allotted to the receivers can be used to record the fault wires of the tester. This leads to an arrangement similar to the one described before with reference to the recording of the translator's fault wires. It should be mentioned in this connection that the translator's fault wires are recorded, not on line 11 but on line 0 of the recording form thanks to the use of a column-shifting relay associated with an auxiliary "memory" relay. Since the tester's fault wires are recorded on line 1 of the recording form, this leads to the use of a second column-shifting relay, referenced PC_q in Fig. 8 and whose function consists in directing to punch magnet P_{11} the ground applied by front contact PC_{13} .

Upon the pulling up of the connecting magnet CV_k associated with the testers of the exchange, the closing of front contact CV_{k5} ground wire t' , with which is associated an auxiliary "memory" relay MKm_{103} . Reference to

the Fig. 10 table will show relay MKm_{103} on line 3 in column 17. When the recording form reaches position 17 as it advances in the perforator, column relay PA_q pulls up and then completes the energizing circuit of column-shifting relay PC_q , which pulls up in turn: battery, relay PC_q , contact PAq_3 , wire r_{103} through cable R, front MKc_{103} , $MKm_{103/1}$, $MKa_{3/4}$, ground.

Front-back contact PC_{q1} of relay PC_q then directs the ground to punch magnet P_1 , the effect of this being to record the fault wires of the corresponding tester on line 1 of the recording form.

It is quite obvious that the foregoing descriptions have been given only as nonlimitative examples and that numerous modifications can be made without thereby departing from the scope of the invention.

Thus, for example, the crossbar switches used to hunt for and to connect common or individual members to the corresponding "memory" relays can be replaced either with rotary switches or with electronic devices using vacuum tubes.

The relay chains described can be replaced with chains of different design but performing the same functions.

Instead of recording the fault wires of the register, receiver, translator and tester in the same columns, although on different lines, it is quite obviously possible to associate a certain number of columns with each member for the recording of its fault wires.

The codes used for the sending of information among the various pieces of equipment can obviously be different from the codes used in the present invention.

The "memory" relays used for the temporary recording of the fault wires can be replaced with (1) magnetic memories, (2) electronic memories using discharge devices, or vacuum tubes, or (3) semi-conductors. Similarly, it is possible to replace the recording form with magnetic-memory devices consisting either of magnetic drums or of multi-track magnetic tapes.

What is claimed is:

1. A telephone system comprising a plurality of common members and a plurality of individual members adapted to be temporarily connected therewith, said members being adapted to control the various selections involved in routing a call, a device for signalling and recording information representing faults likely to affect

35 a seized common member and the various members temporarily connected thereto comprising an auxiliary memory, a fault recorder, means for successively connecting the seized common member and the various individual members temporarily connected to said common member

50 at the moment the fault occurs to said auxiliary memory, means in said auxiliary memory for thereupon sending to said fault recorder the information received, and means for thereupon releasing said auxiliary memory.

2. A telephone system, as claimed in claim 1 further

55 comprising a time device associated with each common member and adapted to control the time taken to perform each elementary operation brought about by the said common member, a finder for said common members, means controlled by each of said timing devices whenever the common member associated therewith takes more than its allotted time to perform said elementary operations for signalling to said finder that that particular common member is in calling condition, and means for causing said finder to cause said auxiliary memory to be connected to said common member in response to said signal.

3. A telephone system, as claimed in claim 2, in which each of the members has a fault wire, means responsive to a fault for placing a potential on a fault wire characteristic of the condition of the circuit connected thereto at the moment the fault arises, the means for connecting the common members to the auxiliary memory comprising means to connect said fault wires to said auxiliary memory to record the characteristic potential appearing on a fault wire so connected.

4. A telephone system, as claimed in claim 2, further comprising means for indicating the identity of a particular common member by the position of the member finder when connected thereto, and means for transmitting the identity of said common member from said member finder to said auxiliary memory for recording thereon.

5. A telephone system, as claimed in claim 4, further comprising means responsive to a completed connection between a faulty common member and the auxiliary memory and the readiness of said memory to record the condition of the fault wires of said common member for causing the temporary release of the member finder and the sending of a special signal to the seized common member, means in said common member for receiving said special signal and for transmitting it to the various individual members with which it is temporarily associated at the instant the fault occurs, means for indicating to the member finder that the first of said individual members is in calling condition and for cancelling the temporary release of said member finder, whereby said auxiliary memory is connected to the fault wire of said first individual member by said member finder, and means for repeating this cycle for each individual member temporarily associated with such common member, whereby said auxiliary memory may record in succession the identity and the condition of the fault wires of said individual members.

6. A telephone system, as claimed in claim 5, further comprising means responsive to the receipt by the auxiliary memory of the identity and the condition of the fault wires of the last individual member seized by the

common member for releasing the member finder after a predetermined period of time, means in response to the release of such member finder for connecting said auxiliary memory to the fault recorder and for transferring the information received by the said auxiliary memory to said fault recorder, means responsive to the recording of the information in the fault recorder for releasing the auxiliary memory, whereby information with respect to the time the fault occurred is recorded.

10 7. A telephone system, as claimed in claim 6, in which there are a plurality of auxiliary memories, whereby the member finder may be connected to a free auxiliary memory while another auxiliary memory is transferring its information to the fault recorder.

15 8. A telephone system, as claimed in claim 7, further comprising a time device associated with a common member controlling only a small number of elementary operations, said time device being adapted to operate after the time taken to perform all of said operations, and 20 means to cause the operation of said time device to place said common member in calling condition with respect to the member finder, whereby it may be connected to the auxiliary memory.
